TELEPHONE SYSTEM

Herbert M. Friendly, Portland, Oreg.; Milton S. Friendly and Central Republic Trust Company, executors of said Herbert M. Friendly, deceased

Application August 6, 1923. Serial No. 655,851

95 Claims. (Cl. 179—18)

The present invention is directed to automatic or machine switching telephone systems; more particularly to systems of the stated general type which contemplate progressing a call from a calling station through the agency of a so-called finger-hole calling dial to a called station wherein mechanism is interposed the purpose of which is to receive and store the directive impulses sent from the dial and then re-send them self-controlled, effective to link the connection from the calling line to the called station. It also comprehends automatic or machine switching telephone systems wherein so-called revertive control is employed to direct the linking operations, 15 in lieu of sending control.

(a) In carrying out the present invention in the exemplified organization chosen to elucidate it, the calling line leads to a lineswitch of well known primary type. The latter switch, in common 20 with other similar switches, has access to a plurality of secondary lineswitches. It will be understood that the primary and secondary lineswitches may be varied as to structural and operative detail; in fact, a so-called finderswitch 25 arrangement may be employed in lieu of said lineswitches to automatically extend a calling line to a trunk line specific to a coordinate movement first selector of the present invention. It is desired to converge the traffic from a plurality 30 of calling lines to a smaller plurality of trunk lines, each said trunk line corresponding to a first selector.

(b) The present invention contemplates automatically extending the connection from the calling line not only to a trunk belonging to a coordinate movement first selector, as stated, but it also contemplates simultaneously extending the connection to an auxiliary, companion coordinate movement selector directly responsive from 40 the calling line, which under certain conditions, as will appear, will cause the said first selector to also operate directly responsive to control means (such as a finger-hole dial) on the calling line after the said auxiliary switch has effected a predetermined portion of the directive movement corresponding to the control impulses sent from the calling line. That is to say, after the said auxiliary selector has effected a predetermined portion of its primary (vertical) movement, the first selector will then become directly operative from the calling line. In the present exemplified organization, after the auxiliary selector has raised its shaft vertically beyond the ninth level, as when sending digit "0" from 55 the sending device constituting the said control

means at the calling station, the first selector will receive one effective directive impulse from the calling line coincident with the auxiliary selector. This, under the condition, will cause the shaft of the first selector to operate vertically into 60 alignment with the first level, and there automatically rotate-in and automatically select a trunk in the said first level. The first level of the first selector will thus contain the "0" trunks that extend from the selector. All other levels 65 of the selector, except the tenth level, contain their respective numerically corresponding trunks. The tenth level may contain the "1" trunks; and in fact, it will appear presently that the physical level position need not in any instance correspond to the numerical trunk group 70 connected thereto. In order to save time in extending connections, it will be advantageous to have the most used trunk numerical groups occupy the lowest levels in the order of their traffic 75 use.

(c) Under the said condition of the digit "0" being sent from the calling line wherein the first selector is caused to rotate-in at the first level, the auxiliary selector will rotate-in one step at 80 the tenth level. The auxiliary selector rotating-in at the tenth level will cause the trunk corresponding to the first selector and the companion said auxiliary selector to be disconnected from the auxiliary selector and extended into operative connection with the first selector, so that the calling line will then be connected to a second selector through the first selector when it seizes the first idle trunk. The auxiliary selector will restore its shaft to normal forthwith upon rotating-in the first step at the tenth level. When the calling party thereafter operates his finger-hole dial in accordance with the second digit of the called line or telephone, the second selector will be directly directly controlled therefrom; the 95 succeeding switches of the connection being similarly directly controlled from the said dial.

(d) If digit "0" is sent, in lieu of digit "0", wherein the shaft of the auxiliary selector is caused to be raised to the ninth level, and not 100 beyond, the shaft of the companion first selector will not be raised from its normal position. However, upon the auxiliary selector rotating-in the first step at the ninth level the first selector will be thereby caused to rotate-in from the normal 105 position and seize the first idle trunk extending to a second selector. Incidental to the said auxiliary selector rotating-in at the ninth level it will thereupon restore its shaft and also cause the trunk extension of the calling line corresponding 110

to the first selector to be disconnected from the auxiliary selector and extended to the first selector so the calling line will now be terminated on the said second selector. When the calling party 6 thereafter operates his finger-hole dial in accordance with the second digit of the called line the second selector will be directly directly controlled therefrom; the succeeding switches of the connection being similarly directly controlled from the said dial.

19 (e) The system used herein to exemplify the invention contemplates that each telephone number of the subscriber lines or stations of the exchange consists of seven digits, the first three of 15 which are nominally the first three letters of an office or exchange district name. Numbers thus expressed are so employed in the method disclosed in U. S. Patent No. 1,439,723 granted to W. G. Blauvelt, December 26, 1922. However, 20 the present system contemplates that alternative calling numbers using only five digits (that is, a lesser number than the prime calling number), the first one of which is indicative of the office or 25 exchange district name. Reference is here made to my pending U. S. application for patent, Serial No. 595,832, filed October 20, 1922, which sets forth a system wherein alternative calling numbers are employed. However, the present system 30 has other new objects over my cited application, as will appear, as well as employing a different operative mechanism and circuits in carrying out its corresponding functional ends.

35 (f) The said auxiliary selectors function selectively at all levels (in the exemplified system), other than the ninth and tenth mentioned, and select the first idle storing device whereby as the finger-hole dial on the calling line is operated successive numerical order elements of the selected storing device are caused to set-up a series of conditions 40 for causing the call to be automatically directly progressed through the first selector and successive switches to the called line, taking into account the various pluralities of trunk links, depending upon the specific call being made, 45 after which the storing device will be automatically self-ejected from the connection; leaving only the selectors and connector or other switches in the connection to the called line. The connection after being thus completed involves switch 50 elements in generally well known relation.

(g) The storing devices belonging to the various level groups differ by being of two general kinds. One kind requires seven digits to 55 completely set it, while the other kind requires but five digits to completely set it. The first digit series sent by the calling party will determine which kind of storing device will be selected and incidentally selects a specific storing device adapted to the concerned call as indexed by the 60 first impulse series sent for progressing the connection to the called line group indexed by the said first series, having in mind that where the first series indexes a train of seven series in all are to be sent, two more series will be required to determine to what ten-thousand line group the call is destined, and also having in mind that where the first series indexes a 65 train of five series in all are to be sent the first series will determine to what ten-thousand line group the call is destined. In order to avoid confusion, it is preferred, though not necessary, to have all listed calling numbers nominally composed of seven letters and digits and corresponding impulse series. However, in the present exemplified system four ten-thousand groups may

be reached from any telephone in the system by sending five series alternatively to the nominal seven, wherein the corresponding last four series are the same in both instances, while a single series is substituted for the nominal first three series. Thus, for calling into any one of four ten-thousand line groups any one of the four corresponding prefixes of three series may be used, depending upon the group being called. In general calling to the four said ten-thousand groups the alternative single series prefix will be used, though if the calling party is not conversant with the expedient, his calling the nominal calling number involving a prefix of three series will cause the call to be completed correctly. In the case of two of the four alternative single series prefixes ("9" and "0" in the exemplified system), the call will be directly directly progressed from the calling telephone finger-hole dial without setting-up a stored condition in a storing device. If the corresponding three-series prefix is called in each case, the storing device will be correspondingly operated and set, and in the case of the three-series prefix corresponding to "9" forthwith restored 100 to normal, incidentally setting up a condition in the first selector equivalent to and the same as would have been set-up therein had the single alternative series been sent. In the case of calling the three-digit series corresponding to "0", the storing device will be set-up to send the digit "1", interpreted from the three-letter prefix, to be followed by the re-sending of the last four (local) digits of the called number responsive to the sending of same from the calling telephone. In the case of sending the three-series prefixes equivalent to the prefixes "7" and "8", the first selector and successive switches will be operated directly from the storing devices and not directly directly from the finger-hole 115 dial of the calling telephone.

(i) In the case of the remaining two of the said four alternative single series prefixes (constituting "7" and "8" in the exemplified system), the storing device selected consequent to the 120 sending of the first series will automatically assume the same equivalent set-up condition for re-sending as if the three nominal prefix series had been sent.

(j) A different kind of storing device is selected depending upon if the first series indexes a prefix of one series or of three series, but if a storing device is reached concerned in a one-series prefix it automatically sets-up a condition equivalent to the three-series prefix storing device wherein the corresponding three-series prefix has been sent effective thereto. Moreover, in the exemplified system, the same storing device is commonly used for the single prefix series corresponding to "7" and to "8", the 130 storing device differentiating depending upon what said single series has been sent to correspondingly seize the storing device from the seventh or from the eighth level. It is possible, and preferable, as will appear presently, to combine the two corresponding classes of storing devices and associate them multiply with the levels indexed by the first series sent, whether the prefix is composed of a single series or three series, so the storing device seized will adapt itself depending upon what level of the said levels it is seized from by the said auxiliary selector. For example, the same group of storing devices under the said arrangement will be accessible from the auxiliary selector at the "7", "8" and "3" 140

80

85

90

95

145

150

levels. In the case of being seized from either the "7" or the "8" level it will forthwith automatically set-up the corresponding three-series prefix, while in the case of being seized from the "3" level it will require the sending of the second and third digits (indexed by letters) from the finger-hole dial to complete the setting-up of this prefix condition. The object of thus multiply connecting the storing devices is to enable using fewer of them than if each level would be required to have its specific, complete storing devices. Where a said auxiliary selector has access to the same storing device from a plurality of levels, a large group of storing devices is thus enabled to be employed in the place of a larger aggregate number of storing devices contained in a plurality of smaller groups. The alternative prefix method would be employed wherein the community served does not require the ultimate letter combination capacity. Under the stated multiple connecting of the storing devices, sending either series corresponding to digit "4" or digit "6", for example, may cause the same group of storing devices to be selected over by the auxiliary selector. In the present exemplified system, "4" is denoted by the letters "G", "H" and "J", while "6" is denoted by the letters "N", "P" and "R". That is, initially operating the finger-hole dial in accordance with any one of the latter six letters will cause the same storing device group to be subject to selection. Of course, more than one office name beginning with any of the said six letters cannot have second and also third letters corresponding.

(k) The present system in its comprehensive adaptation thus contemplates permitting certain ten-thousand groups being reached by sending five impulse series from a calling telephone, whereas all other ten-thousand groups called from the said telephone will require seven digit series to be sent. The ten-thousand groups reached by five series may differ throughout the system. For example, in the business district of a city, which may comprise four ten-thousand groups, the telephones may be provided for mutually calling by five series, as well as the listed seven. At the same time, the residence sections of the city may have telephones of their own containing ten-thousand group attainable by five series, as well as three other ten-thousand groups at random as traffic characteristics warrant without regard to the offices which may be prefixed alternatively when calling them from other offices. The finger-hole dials will have the office or ten-thousand group name visible through the corresponding finger-hole, as well as other letters and the Arabic digits arranged numerically. Of course, the letters associated with the named digit finger-holes will not refer to a first digit of a prefix, so that any letters appearing in the digit finger-holes "7", "8", "9" and "0" cannot, in the exemplified system, be used as first letter of a prefix of three series, but may be used as second or third series of a prefix. For example, the letters "S" and "T" appearing as alternatives for digit "7", wherein the name prefix "Dairy" also appears, cannot be used as a first letter in a three-letter prefix, as in that case the prefix "Dairy" would be effectuated.

(l) A modification of the plan outlined provides for introducing a finderswitch equipment intermediate of the trunk corresponding to the first selector and the said auxiliary selector whereby a fewer number of the said auxiliary

selectors than first selectors may be employed, since after the first selector seizes in some calls and when the connection is completed to the called line in others the said auxiliary selector is disconnected from effective operative relation with the circuits employed in the call. So where the finderswitch arrangement is used, the auxiliary selector is then subject to further use after its use in the last call has terminated.

(m) The present system provides means for separately metering the calls destined to the various ten-thousand groups over specific trunk routes, so that record of the traffic from the various offices to called offices can be automatically recorded. The meters are associated with the storing devices.

(n) A salient feature of the present system is that function thereof which provides for automatically variably spacing the different series in a train sent from the storing device for completing a connection. An object of this function is to allow or provide a greater switch hunting time between any desired successive series of any specific stored call without affecting the spacing of successive series in any other call wherein the same calling line and the same storing device may be concerned. This admits of employing secondary non-numerical tandeming switches or combination numerical and non-numerical switches in one switch. It also admits of employing non-numerical switches in secondary relation to a selector level whereby a said switch corresponds to each bank position of the concerned level so when a said non-numerical switch is seized it will forthwith hunt over a subordinate group to extend the call to the selector of the next higher order from the one last seizing. The normal hunting time will possibly be exceeded, due to the double selection. To increase the hunting time between all series sent universally would prolong the re-sending to a prohibitive, or at least undesirable period. The spacing between digit series will therefore be consistent with the specific trunk routing of the calls to all ten-thousand groups, and is determined by the prefix from predetermined connections in the storing device concerned in each possible trunk routing.

(o) A salient feature of the present invention is the function, and means for effectuating the said function, whereby if all trunks in a group attained by any one of the prefix series sent from the storing device are found busy, whereby the selector testing the said busy group will rotate over all the busy-test contacts, the progressed connection will be thereupon automatically destroyed and the call then automatically re-progressed over another route to the ten-thousand group containing the line leading to the called telephone. The latter stated function permits a less factor of margin in the number of trunks provided over certain routes, because in the event of a temporary shortage of trunks the call will be given a route, possibly less direct, which may at the time have ample margin of idle trunks as regards their normal traffic uses. When a selector fails to find an idle trunk its shaft in rotating its wipers over all the trunk positions causes a cam on the shaft to operate a set of springs which will reverse the direction of current towards the storing device. This latter function will cause an electro-polarized relay in the auxiliary selector to actuate to cause the first selector to restore and to cause the so-called digit distributor switch of the storing device to

- return to normal position and automatically re-initiate its functioning to transmit the first directive series of the alternative prefix series train. Coincident with the restoration of the digit distributor switch, a relay will actuate to change the set-up condition as relates to the prefix series set-up corresponding to the primary trunk route to an alternative set-up condition corresponding to the alternative trunk route as relates to the normally set-up condition directly set-up by the calling party manipulating his finger-hole dial. When the storing device sets its wipers responsive to a three-letter prefix sent by the calling party, it effectively sets-up a stored condition corresponding to a primary or preferred trunk route and also sets-up one additional (or more, as provided for) stored condition corresponding to an alternative trunk route. So when the call cannot be forthwith completed to its ten-thousand group due to all the trunks being busy, or are busy-guarded because of an out of order condition occasioned by reason of a trunk cable failure, perhaps, the progressed portion of the call from the first selector is destroyed and the storing device will then become capacitated to forthwith automatically directly extend the call in the direction of the called line over the alternative route. A method is shown wherein if the second set-up condition is found to correspond to a busy trunk group as before, a third set-up condition will become effective to again cause the connection to be progressed in the direction of the called line over a second alternative trunk route.
- (p) Another feature of the present system is the group impulse sending device whereby a single motor or other driver will operate senders for a plurality of storing devices wherein a practically constant interval will elapse between digit series re-sent, subject, however, to the function for varying the spacing referred to in paragraph "n".
- (q) Another feature of the system is the auxiliary selector employed as an element of the storing device where two series are used as a prefix in lieu of three. This would be employed in the system wherein when the system is primarily installed six-digit numbers are assigned to subscribers, of which the last four digits are the local or called office digits, while the first two digits correspond to the prefix letters wherein only the first two letters of the office name have calling significance. Upon the system expanding, the storing devices will be suitably modified to employ the three-digit prefixes consisting of the first three letter equivalents of the office names so that the storing device is not then selected until after the first series of the prefix is sent effective to operating the auxiliary selector in its primary direction.
- (r) A feature of the storing device employed in the system provides for shortening the space between the last two digit series of a called line or telephone number so that the usual hunting time provided for testing for an idle trunk of the group selected following the primary series effective to the switch will not ensue, since the connectors (as in the exemplified system) may be wholly step-by-step directive controlled until the called line or trunk of a sub-group is reached and tested.
- (s) It has been deemed expedient to first disclose the general operating plan of the system by drawings which omit certain details of the system in its most comprehensive organization

contemplated, and then to disclose various detailed features by means of drawings disclosing the modifications applied to the general operating plan shown in the first said drawings.

(t) It will be understood that in a comprehensive exchange system, as contemplated, the traffic conditions, and also the geographical conditions of each ten-thousand group or each office group will determine what specific form of equipment organization will be best suited. Thus, so-termed modifications and adaptations, and also the said first disclosed operating plan will be incorporated in the system and perhaps changed from time to time as traffic changes demand. For example, certain offices may have a group of dual functioning storing devices as has been referred to common to a plurality of auxiliary selector levels, while this expedient may not be employed in other offices. Again, certain offices may employ alternative calling prefixes constituting a name, and therefore requiring but one pull of the finger-hole dial while other offices may require three letter series and corresponding said pulls for all prefixes of numbers called. That is, some offices may not be provided for the said alternative prefix calling. Again, certain offices may employ a first and also a second alternative trunk route to all or only to certain other offices, while other offices may employ a single alternative trunk route to all or only to certain other offices. Also, only a part of the storing devices of an office may have provision for effecting alternative trunk routing or only certain offices called therefrom may be reached by alternative trunk routes. Moreover, different subscriber groups of an office may have different alternative outgoing trunk routes respectively, to some office or offices, so in the event of abnormal traffic or a trunk cable failure, the collective "overflow" traffic from the concerned calling office will be diverged over a number of alternative trunk routes though each line calling may possibly have but one or two alternative routes to a called office.

The system contemplated in the present invention thus comprehends the use of generally similar equipments in the various offices of the system so as to effect cooperation, but it will be understood that the details of structure and organization will differ in the various offices or groups of the system as set forth with relation to the so-termed modifications and adaptations. The present disclosure is to be understood as merely illustrative, and not exhaustive. The scope of the invention is therefore defined by the broadest interpretation of the subjoined claims.

While the descriptions following relate to a certain calling telephone CT and its tributary office, this is to be understood as merely a convenience of disclosure wherein the varied assemblies may refer to as many different calling telephones and tributary offices. The trunks used in the system are in groups extending between offices; between offices and switching centers; between switching centers and offices; between switching centers in a universal interswitching network. Only the trunk groups employed in the assumed calls relating to one assumed calling office have been shown. Certain of the inter-office trunk groups shown may commonly serve other calling offices not indicated.

Referring to the drawings:—

Fig. 1 shows a calling telephone CT leading to a primary lineswitch PL wherein the said switch, 150

in common with other similar switches, has access over a trunk to secondary lineswitch SL.

Fig. 2 shows a trunk accessible from the secondary lineswitch SL, in common with other similar switches, leading to first selector S2.

Fig. 3 shows an auxiliary selector AS3, auxiliary to first selector S2, and which is normally operatively associated with the trunk adapted to lead-in to first selector S2.

Fig. 4 shows a portion of a storing device adapted to be selected by auxiliary selector AS3 at the 3rd level.

Fig. 5 shows the remaining portion of the storing device shown in part in Fig. 4. Fig. 5 is also adapted to cooperate with Figs. 6, 9, 10 and 18.

Fig. 6 shows a portion of a storing device adapted to be selected by auxiliary selector AS3 at the 7th and 8th levels.

Fig. 7 shows a modification of Figs. 4, 6 and 19, wherein the number of calls over the different inter-office trunks as segregated into groups related to a called office can be metered.

Fig. 8 shows a finderswitch mechanism for introduction between Figs. 2 and 3, so lines extending to joining margins register, in order to obviate employing an auxiliary selector as AS3 permanently companion to the trunk companion to first selector as S2, and whereby a said auxiliary selector will commonly serve a plurality of first

selectors as S2.

Fig. 9 shows a modification of the storing device portions shown in Figs. 4 and 6 whereby combining Fig. 9 (in view of Fig. 4) with Fig. 5 so the lines extending to the joining margins register will serve the same objects as Figs. 4 and 5, and as Figs. 6 and 5 similarly combined. That is, Figs. 9 and 5 combined, disclose a storing device which will set-up a stored condition consequent upon being seized, or consequent upon

being directly operated after its seizure, depending upon the level at which it is seized.

Fig. 10 shows a modification of the storing device Figs. 9 and 5 combined, whereby if a selector in extending a connection to a ten-thousand group encounters all inter-office trunks of a group busy, the so-far extended connection will be destroyed. A predetermined alternative set-up condition as relates to the prefix of the called line will automatically ensue, displacing the one initially set-up, will become forthwith effective to again extending the connection over a new inter-office trunk route in the direction of the ten-thousand group containing the called line.

Fig. 11 shows a modification of the selectors S2 and AS3 in Figs. 2 and 3 respectively, to carry out the objects contemplated in Fig. 10.

Fig. 12 shows a well known selector into which is introduced a set of "last rotary" cam-springs LR for reversing the direction of current over the leading-in trunk to the selector towards the calling end. This selector would be employed as are selectors S2, B and C, for example, having in mind the requirement of off-normal spring 225 in selector S2. The said cam-springs LR operate from a shaft cam after all trunk positions of a level have been tested and found busy.

Fig. 13 shows a combination of well known bridging repeater BR and a well known series repeater SR with the same outgoing trunk.

Fig. 14 shows a rear elevation of the impulse sending device.

Fig. 15 shows a side elevation of the device shown in Fig. 14.

Fig. 15A shows the motor and worm drives for

the impulse sending device shown in Fig. 14 and the impulsing cam 510 in Fig. 5.

Fig. 16 shows a front elevation of the impulse sending device shown in Fig. 14.

Fig. 16A shows the tooth drive wheel 438' shown in Figs. 14, 15 and 16.

Fig. 16B shows one leave of the laminated pole-piece 446'-447' shown in Figs. 14 and 15.

Fig. 16C shows a spacer for carrying one end of the strut 464' in Fig. 14.

Figs. 16D and 16E show a bottom plan and side elevation respectively of the dog 450' in Fig. 15.

Figs. 16F and 16G show front and side elevations respectively, of the left-hand portion of the yoke element 433' shown in Fig. 15.

Figs. 16H and 16I show the side and front elevations of the right-hand portion of the yoke element 434' shown in Fig. 15.

Fig. 17 joined above Fig. 18 so the lines extending to the joined margins register shows a modification of Figs. 4, 6, 9 and 10 wherein two and three prefix set-up conditions are coincidently set-up; the set-up conditions being effective successively if the call cannot be completed to a ten-thousand group due to a busy trunk condition wherein each set-up condition refers to a different trunk route from the calling to the office terminating the called line.

Fig. 19 shows detail modifications of Figs. 17 and 18.

Fig. 20 shows a modification of Fig. 3 and a portion of the storing device shown in Figs. 4 and 5 for enabling a prefix to be set-up by sending one and two digits in lieu of one and three digits.

Fig. 21 shows a diagram of equipment elements and inter-office trunks with reference to a calling office and six lines of respective called offices of the system.

Fig. 22 shows a diagram of the calling office, inter-office trunk-switching centers and called lines with relation to certain calls to be assumed.

Fig. 23 is a plan view of the finger-hole dial of the present invention.

Figs. 24 to 28 show the assembly of the figures to incorporate various organizations of equipment elements employed in the system of the present invention.

Fig. 29 shows a modification of Fig. 10.

Fig. 30 shows a modification of Fig. 21.

The various equipment elements will be comprehended in view of the following references to the Third Edition of "Automatic Telephone Practice" by Harry E. Hershey. The subscribers' telephones or substations are the usual common battery series type including a finger-hole dial calling device as described on pages 16 to 19; the primary lineswitch PL and the secondary lineswitches SL, N', P' and PP' are as described on pages 53 to 55; the finderswitches F8 and F'8 are

of the general type as the finderswitch described on pages 156 and 157, though modified to operate in accordance with the present invention; the various selectors and the auxiliary selector AS3 are as described on pages 59 to 62, having in mind that first selector S2, auxiliary selector AS3 and the selector shown in Fig. 12 are modified to operate in accordance with the present invention and that selector P'' has a normal level like selector Fig. 18 shown in my pending U. S. application for patent, Serial No. 171,637, filed May 29, 1917; the connectors are as described on pages 36 to 40; the rotary switches or elements of the impulse storing device, wherein a stepping magnet is employed, are of the general type as switch

140

145

150

PL as to mechanical structure, having in mind that the said elements in the storing device operate both step-by-step directively and non-directively.

5 The detailed operation of the elements of the system and the system itself will be comprehended in view of the calls which will be exemplified. Only enough of the system contemplated in the invention is shown and described as has been 10 thought necessary to a full and complete disclosure of its operating principles and organization.

Attention is called that Fig. 5 may be independently combined with Fig. 4 and with Fig. 6, wherein both said organizations are assumed 15 simultaneously operative. This method of disclosure has been chosen and generally applied to avoid duplication.

Refer to Figs. 21, 22 and 24 and assume that the party at telephone CT removes the receiver 20 from the switch-hook to initiate a call destined to telephone TF. The primary lineswitch PL and the secondary lineswitch SL will each seize the first accessible trunk successively. The trunks thus seized are to be assumed to be the ones the 25 respective sets of wipers of the said switches are shown resting upon. An energized circuit can now be traced from the free terminal of upper winding of line relay 301, conductor 302, make-before-break spring 201, conductor 202, wiper 301, armature 102, wiper 103, armature 104, conductor 105, telephone CT, conductor 106, armature 107, wiper 108, armature 109, wiper 112, conductor 113, make-before-break spring 204, conductor 205 to the free terminal of lower winding 30 of relay 301, the latter said relay actuating, followed by slow-releasing relay 303. Ground can now be traced from armature 305, conductor 306, armature 207, conductor 208, wiper 115, armature 116, conductor 117, wiper 118, armature 119, winding of switching relay 121 to battery attached 40 to the winding of stepping magnet 122. Switching relay 124 is energized in a path from battery, winding of stepping magnet 125 to conductor 117.

The calling party at telephone CT can now 45 cause the call to be completed to the called telephone TF, the telephone number of which is "EDITOR-5642"; that is, by sending digits "331-5642." It can also be completed alternatively by operating the finger-hole designated 50 "Editor", followed by digits "5642"; that is, by sending digits "9-5642".

It will first be assumed that the three-letter prefix "EDI" (corresponding to digits "331") is sent, followed by the local digits "5642". The latter said four local digits is representative of the numerical position occupied by the called line terminals in the ten-thousand group to which it belongs. Upon sending the first prefix letter "E" (corresponding to digit "3") the relay 301 will 60 vibrate, its grounded armature correspondingly causing three ground impulses to be applied through armatures 308, 309, winding of slow-releasing relay 310 to the vertical magnet VM3, the relay 310 actuating and sustaining over the 65 lapses so that ground will be applied from conductor 306, armature 312, off-normal springs to the winding of shunted interrupter relay 313 to actuate and lock the latter said relay through armature 316 on the rotary magnet RM3 and armature 317 on said relay 313. When the 70 impulses (three) have been sent and relay 310 de-actuates, ground from conductor 306 will be applied through armatures 312, 320 to the rotary magnet, causing it to rotate the wipers 321 to 75 324 (inclusive) one step into engagement with

the first set of bank contacts 331 to 334 respectively. The well known automatic selective operation will take place (in view of the citation) wherein switching relay 326 will remain short-circuited to ground at both its terminals as long as private wiper 321 encounters busy ground. However, assuming that the bank contact 331 first engaged does not index a busy state, and therefore is ungrounded, when armature 317 retracts the ground will be removed from the upper terminal of the winding of relay 326, causing the latter said relay to energize in series with the shunted winding of relay 313. Relay 326 only, will actuate due to the marginal adjustment of relay 313. Ground is thus applied through armature 328, wiper 321, bank contact 321, conductor 335, armature 401 to the winding of relay 402, the latter said relay actuating. Relay 301 being still energized in series with telephone CT, the ground on conductor 306 will serve to hold auxiliary selector AS3 and its antecedent switches seized, dependent upon the switch-hook at telephone CT. A circuit path can now be traced from armature 308, armature 309, wiper 322, bank contact 322, conductor 336, winding 100 of slow-releasing relay 403, wiper 404, bank contact 408 to the vertical magnet VM4 of switch SD4. A circuit can also be traced from the lower winding free terminal of relay 339, lower armature of relay 326, wiper 323, bank contact 105 333, conductor 337 to grounded armature 500, relay 339 actuating. A circuit can now be traced from the winding free terminal of the line relay 212 in first selector S2, armatures 213-214, 215-216, conductors 217-218, respectively, 110 and including armature 340 on relay 339. Relays 212 and 219 will actuate in sequence, armature 221 applying a supplemental ground to conductor 208.

The coordinate movement switch SD4 has a 115 mechanical structure similar to the connector cited, though no talking conductors are concerned therein. The shaft can be driven vertically by the vertical magnet VM4 ten steps and then rotarily by the rotary magnet RM4 ten 120 steps at any vertical level position. The release magnet Re4, energized through shaft off-normal contacts ON4 is operative to restore the shaft of switch SD4 to normal. The said shaft carries four wipers 411 to 414. There are one-hundred 125 contact sets, each set consisting of four bank contacts adapted to register with the wipers 411 to 414 respectively. The said bank contact sets occupy ten vertical level positions wherein there are ten sets mounted laterally at each level. Six 130 sets are shown; these being assumed to be the first three sets in each the second and third levels. That is, the lowermost sets shown occupy bank positions "321" to "323", and the uppermost sets shown occupy bank positions "331" to 135 "333".

In this connection, it will be understood that there will be a plurality of storing devices as shown in Figs. 4 and 5 combined as indicated in Fig. 24. One such storing device will occupy 140 each lateral or rotary position of the third level of auxiliary selector AS3. This will also hold for certain other levels of the auxiliary selector AS3; the 4th, 5th and 6th, for example. However, it will appear presently that contact sets 145 of the storing devices will be wired differently as respects the different levels of auxiliary selector AS3. The storing devices reached from any specific level of said auxiliary selector AS3, being alike, it will not make any operative differ- 150

ence which one in the attained level is the first found idle, having in mind there are a plurality of companion selectors similar to AS3 commonly accessible to a plurality of storing devices at 5 certain or all vertical levels, depending upon the capacity of the system. In the present exampled system, one level, the third, is the only one provided with storing devices of the type disclosed in Figs. 4 and 5 combined, and it will appear 10 presently what salient wiring difference of the bank contact sets differentiates the storing devices as regards the various levels of the auxiliary selector AS3.

Assume that the calling party now sends the 15 second prefix letter "D" (corresponding to digit "3" as in the case of the first prefix letter "E"). The armature of relay 301 will correspondingly vibrate and apply three ground impulses over the traced path to the vertical magnet VM4, 20 which will cause the wipers 411 to 414 to be raised three steps into alignment with the third level of bank contact sets. At the time the first impulse is applied through the winding of relay 403 it will attract its grounded armature 407 and sustain it over the lapses between the remaining 25 two impulses, after which the said armature will retract consistent with its slow-release characteristic, following the last impulse. The stepping magnet SM4 will thus be energized while the said digit series is being sent, preparatory to 30 advancing the wipers 404 to 406 one step so wiper 404 will then rest upon bank contact 409 and wiper 406 will then rest upon bar 410 when the armature 407 retracts.

The calling party will now send the third 35 prefix letter "I" (corresponding to digit "1"). One ground impulse will be applied from the armature on relay 301 over the traced path to wiper 404, bank contact 409 to the rotary magnet RM4, causing the wipers 411 to 414 to be rotated one step and set into engagement with bank contacts 421 to 424 respectively. Bank contacts 422 to 424 are unconnected. The wipers 404 and 405 will advance to bank contacts 416 and 417 respectively, at the termination of the impulse series effective to the rotary magnet RM4. Therefore, upon armature 407 retracting, following the setting of wiper 411 upon bank contact 421, a circuit path can be traced from grounded wiper 405, bank contact 417, bank contact 419, wiper 426 of set 425 to 429, armature 430 to the winding of stepping magnet SM'4. This closes a self-interrupting circuit path for stepping magnet SM'4, causing the wipers 425 to 429 to advance 50 so wiper 426 will then disengage contact 419 and rest upon bar 442. Ground from bank contact 431 will be applied over wiper 428, armatures 432 and 433, conductor 434, winding of relay 501, armature 502 to magnet M5. However, before 55 magnet M5 has had time to become operatively effective, its said traced energizing circuit will become opened at armature 433 as will appear presently due to ground applied through the winding of marginal relay 435, make-before-break spring 436, wiper 429, bank contact 437, wiper 411, bank contact 421, resistance 438, conductor 338, bank contact 334, wiper 324, armature 341, conductor 342, off-normal spring 225 to the winding of shunted interrupter relay 227 and also from conductor 342 through make-before-break spring 229 to the winding of trunk switching relay 230. Relays 227 and 230 will 60 coincidently operate, while relay 435 remains inert due to the inclusion of resistance 438.

75 The actuation of relay 230 will cause the trunk

talking conductors 202 and 213 to be continued through armatures 213 and 214 to the free terminals of line relay 212, respectively. Relay 212 is now energized in series over the traced path including telephone CT in lieu of the traced path including armature 349. Also, the ground on conductor 208 now emanates from armature 221 in selector S2 in lieu of armature 305 in selector AS3. Conductor 306 is disconnected and relay 230 is locked to conductor 208. Conductors 302 and 205 are disconnected so that relays 301, 303 and 326 deactivate, closing a circuit from grounded armature on relay 301, armature 308, off-normal springs to the release magnet Re3, operative to restore the auxiliary selector AS3. 80 The relay 227 actuating coincidently with relay 230 causes a circuit to be closed from conductor 208, armatures 235, 236 to the rotary magnet RM2 effective to rotate the wipers 241 to 243 from normal into engagement with normal level bank contacts 245 to 247 respectively and incidentally operate the off-normal spring set VR2. The latter said off-normal set operates consequent to a rotary or vertical off-normal movement of the shaft carrying wipers 241 to 243. If 90 wiper 241 encounters busy-ground on bank contact 245, relay 227 will become locked, preparatory to rotating the wipers 241 to 243 an additional step. The selector S2 of the present invention functions as a well known selector in view of the citations, having in mind, however, that it is functioning with reference to the normal level in this instance. It will seize in the well known manner consequent to its switching 95 relay 249 actuating when an ungrounded busy-test contact of the first idle trunk tested is encountered. By reference to Fig. 21 it will be noted that selector W has been seized, leading from the first set of bank contacts of the normal level of selector S2. Had selector W been found 100 busy, the wipers 241 to 243 would be automatically caused to rotate and successively test the trunks corresponding to the selectors of the group containing selector W and seize the first idle one found; the selector W and the selectors of its 105 group having common access to the same group of trunks. Annexing the local digits "5642" will progress the call through the banks of local selectors W and Y and the connector Z to the called line leading to telephone TF directly 110 directly in the well known manner in view of the citations.

At the time auxiliary selector AS3 restores relay 402 deactuates. Under the latter condition ground derived through the winding of slow-releasing relay 440 is applied to the armatures of relay 402 and a busy-ground is applied through armature 401, conductor 335 to bank contacts 331 and its multiples related to auxiliary selectors of the group containing auxiliary selector AS3. 115 Bars 410, 442, 505 to 508 will thus be grounded. Said bars 505 to 508 are not engaged by a wiper at this time. However, wiper 406 is in engagement with bar 410 and wiper 426 is in engagement with bar 442. This will cause the stepping 120 magnets SM4 and SM'4 to automatically function to rotate the wipers from the said engaged bars respectively, and into engagement with the next bank contact, which is the contact upon which the concerned wipers normally rest, as shown in 125 the drawings. The release magnet Re4 will be operatively energized to restore the wipers 411 to 414, so that the apparatus shown in Figs. 4 and 5 is automatically restored to normal upon the restoration of auxiliary selector AS3. Any condi- 130

135 140 145 150

tion set-up by the brief energization of magnet M5 will be automatically effaced consequent to its deenergization, as will appear presently. The relay 440 will remain energized until after ground 5 has ceased to be derived through its windings, to insure busy-guarding the storing device shown in Figs. 4 and 5 until it restores to normal. Under the condition of relay 440 being actuated a hunting auxiliary selector of the group containing 10 selector AS3 will be barred from the specific storing device, and so will selectively test the next succeeding set of bank contacts corresponding to 331 to 334 as has been referred to.

The connection between the calling and called 15 line involves the same switches as is a well known practice, having in mind the novelty of the added relay 230, off-normal spring 225 and the normal bank level of selector S2. Upon the calling party replacing his receiver the ground will be removed 20 from conductor 208 so that relays 249, 124 and 121 will deactuate, whereupon the circuits concerned are at normal.

In this connection, it will be noted that the 25 storing device (which is common to a plurality of trunks and corresponding auxiliary selectors, such as AS3) is released for new service consequent to the sending of the third prefix letter. The selector W may be located in the same ten-thousand group as the first selector S2 or it may 30 be in a remote office containing telephone lines belonging to a different ten-thousand group than the calling telephone. In order to avoid extending more than the talking conductors to selector W, if located remotely to selector S2 a trunk 35 repeater of well known type (in view of the citation made hereinafter) would ordinarily be introduced and is represented by the small circle in the trunk leading to said selector W. Similar repeaters are shown in other trunks in Fig. 21, 40 having in mind that wherever repeaters are employed in the present system any type may be used, depending upon the conditions and length of trunks. Moreover, as indicated in Fig. 21, where a trunk may be used alternatively as a 45 complete link or as a component element of the link wherein a plurality of trunks are tandemmed to form a link, provision is made so as to not introduce more than one repeater in the link. That is, the second trunk introduced into the connection will have its repeater by-passed. However, if the said second is the first trunk of a 50 link or the only one thereof, it will be seized through its companion repeater. This will also insure the calling telephone receiving talking 55 battery from the nearest two-wire trunk if one is used in the connection. For example, the incoming selectors of inter-office trunks will seize the trunk shown in Fig. 13 through the device SR, while the local outgoing selectors having common 60 access to a said inter-office trunk will seize it through the repeater BR. The repeater BR indicated in Fig. 13 may be assumed, for example, the repeater shown on pages 76-77 in the said cited book of Hershey's.

65 Assume that in lieu of sending the three-letter prefix "EDI", the single alternative name prefix "Editor" is employed as would generally be the case in commercial service. In this instance the finger-hole dial will be first operated from the 70 "9" finger-hole also designated "Editor", to send a series of nine impulses, causing the wipers 321 to 324 to be raised into alignment with the ninth level of bank contacts and rotate-in and test in the manner before stated. However, there are no 75 storing devices associated with the ninth level.

The bank contacts engageable to all the wipers 321 to 324 being unconnected, excepting only the first bank contact 349 of the ninth level engageable to wiper 324 when it rotates-in in the manner stated with reference to the third level. When 80 wiper 321 engages first bank contact 350 of the ninth level, and finds no ground, the auxiliary selector AS3 will seize through relay 326 actuating. A circuit path can now be traced from grounded bank contact 349, wiper 324, armature 341, conductor 342 to the windings of relays 230 and 227, causing the same functioning in first selector S2, followed by the restoration of auxiliary selector AS3 as before described when the three-letter prefix "EDI" was sent. However, in 85 the present instance, the grounding of conductor 342 is responsive to the sending of one impulse series in lieu of three. The completion of the call over the route previously taken will be directly 90 directly accomplished responsive to the sending of the last four (local) digit series.

95 Assume that the said initiated call was destined to telephone TE, the telephone number of which is "FEDeral-2353"; that is, the call can be completed by sending digits "333-2353". It can also 100 be completed alternatively by operating the "0" finger-hole also designated "Federal", followed by local digits "2353"; that is, by sending digits "0-2353". It will first be assumed that the three-letter prefix "FED" (corresponding to 105 "333") is sent, followed by local digits "2353". Responsive to sending the said three-letter prefix, the auxiliary selector AS3 and the switches SD4, DS4 and ND4 and first selector S2 will function as when the three-letter prefix "EDI" was 110 sent, except that in the present instance the wipers 411 to 414 will be raised three levels and set upon bank contacts 445 to 448, respectively. Ground will not be applied to bank contact 334 from conductor 338 so the relays 227 and 230 115 will not be caused to actuate consequent to the said setting of wipers 411 to 414.

120 Before detailing the operative functioning of Figs. 4 and 5, reference is made to the digit finder DF5 in Fig. 5 shown in mechanical detail in Figs. 14 to 16I. The said digit finder DF5 corresponds to the digit finder DF6 in my pending U. S. application for patent Serial No. 595,832, filed October 20, 1922, and moreover, one may be substituted for the other.

125 Referring to said Figs. 14 to 16I, a motor M15 drives a shaft 401' through an intermediate worm-gear 501' and 502' whereby the shaft 401' will revolve at a rate of approximately once in twenty-five seconds, or that the angular distance 130 of ten teeth on the wheel 438' carried rigidly on the said shaft will be rotated each second so as will appear presently the impulses will be sent from the device at the rate of approximately ten per second. The said shaft 401' is common to a plurality of digit finders spaced at length on the shaft. The metal standard 403' has a magnetic metal plate 405' attached to it by four screws 406'. The plate 405' carries a set of insulated bank contacts 411' to 420' and a solid bar contact 425' having a connecting lug 426'. Insulated wipers 431' and 432' engage the bar 425' constantly and the contacts 411' to 420' successively when turning about the shaft as an axis. A yoke mounting for the wipers 431' and 145 432' is shown in Figs. 16F, 16G and 16H, 16I respectively. The said parts 433' and 434' have slots which admit of centering them on the shaft 401' after being assembled with the wipers 431' and 432'. A bearing sleeve 435' through which 150

the shaft passes is rigidly secured to the standard 403'. A spacing sleeve 436 fits movably over the outside of the bearing sleeve 435'. The assembled yoke parts 433' and 434' are then passed 5 over the shaft on either end of the sleeve 436' and the latter said sleeve and yoke then slidably moved to the right over the sleeve 435', the bearing portions of parts 433' and 434' revolvably fitting over the sleeve 435'. The toothed 10 wheel 438' is then placed upon the shaft 401' and moved to the right so its hub becomes flush with the left-hand end of the sleeve 435', which latter extends slightly beyond the left-hand face of part 433' so as to insure not binding the yoke 15 assembled from the parts 433' and 434'. A flat spiral spring 441' is coiled about the sleeve 436' and secured to the part 433' by a stud 442' and to the standard 403' by the stud 443'. An electro-magnet core 445' is secured to the standard 20 403' and carries two similar iron pole-pieces 446'-447' (one only, shown in Fig. 16B) assembled reversed. The said pole-pieces 446'-447' are slotted radially to enable them to be placed over the shaft 401' and then assembled by the 25 screw 448'. An iron pawl 450' (shown in Figs. 16D and 16E) is pivoted between the formed jaws 601' and 602' in Fig. 16I and held upright by the tension of the flat spring 452'. The pawl 450' passes through the rectangular slot 456' 30 in part 433' and is fitted snugly, but slidably. A downward projection part 455' is secured between the formed sides of the pawl 450'. The pole extensions 457' are attractively related to the pole-pieces 446'-447' so that when the electro-magnet winding on the core 445' is energized 35 the pawl 450' will be movably attracted to the bottom of the slot 456' at which position the projection 455' will fall within the outer circumference line of the teeth on the wheel 438'. Having 40 in mind that the wheel 438' rigidly attached to the shaft 401' is revolving constantly, the first tooth on the wheel 438' to encounter the projection 455' will carry the pawl 450' and the attached yoke mounting the wipers 431' and 432'. The pole-piece 457' is prevented from making 45 contact on the pole pieces 446'-447' due to the pawl 450' resting on the bottom of slot 456' and the projections 461'-462' are provided to mechanically disengage the projection 455' from an engaged tooth in case the pole-pieces 446'-447' do not unmagnetize before the pawl is carried to that angular point. The projection 461' on the pole-piece in the direction the wheel 438' 50 is revolving is the only one having operative purpose. The strut 464' is mounted by two posts secured by screws 465'-466'. One post 467' is shown in Figs. 15 and 16C. Screws 469'-470' attach the pole-pieces 446'-447' to the strut 464' to secure the pole-pieces more firmly than 55 by the screw 448' alone. The wipers 431'-432' are electrically tied so the bar 425' will be successively tied to the bank contacts as 411', 412' to 420' as the wipers are rotated with the shaft 401'. The off-normal springs 505' to 508' are 60 held operated (as shown) by the tension of coil spring 441' when the yoke assembled of the parts 433'-434' is at normal. The vertical position of the wipers in Figs. 14, 15 and 16 is an off-normal position which may be assumed as manually created since in no event could the wipers be maintained in an off-normal position if the pawl 450' is normal or the springs 505' to 508' are normal as shown. The placing of the wipers in the vertical position has seemed the simplest in illustrating the device.

It will be clear that if the electro-magnet 445' deenergizes at any time, which it will appear presently will occur when the wiper 432' engages a grounded bank contact, the pawl projection part 455' will disengage from the tooth of the wheel 438' and the spring 441' will cause the wipers 431'-432' to retract to normal and operate the off-normal springs 505' to 508' into the positions shown.

The cam 510 operating the spring set 512 shown in Fig. 5 is so timed that it will operate the spring set 512 one time for each angular revolving of the shaft equal to the angular spacing of the bank contacts engaged by wiper 432'. The latter angular spacing corresponds to the angular spacing of the teeth on the wheel 438'. The operation of spring set 512 will occur when the wipers 431'-432' are approximately midway between two adjacent bank contacts engageable to wiper 432'. It follows that as many impulses will be sent from spring set 512 during the time the wipers 431'-432' are off-normal as there are off-normal bank contacts engaged by wiper 432' while being driven from normal position, it normally resting upon an unconnected bank contact. It will become clear that for each digit series the wipers 431'-432' will be drawn clockwise and released to restore to normal under the tension of spring 441' and incidentally flex the off-normal springs 505' to 508' into the position as shown in Figs. 16 and 5.

Continuing the description with relation to the set-up condition in Figs. 4 and 5, it will appear presently that the condition set-up consequent to the setting of wipers 411 to 414 upon bank contacts 445 to 448 respectively, responsive to the sending of the three-letter prefix "FED" is that which will cause the digit "1" to be sent effective to the shaft of first selector S2, whereby the calling line will be progressed to selector T. In accordance with the sending of the last four (local) digits "2353" from the calling line, the same said digits will be re-sent operative successively to selectors T and U and connector V, as will appear presently.

When the grounded wiper 405 engages bank contact 417 and causes the wiper-set 425 to 429 to advance a step, a circuit path can thereafter be traced from ground, winding of relay 435, spring 436, wiper 429, bank contact 437, wiper 411, bank contact 445, digit conductor 1, resistance and conductor to bank contact 411' (corresponding to digit "1") of the digit finder DF5. A circuit path can also be traced from grounded bank contact 431, wiper 428, armatures 432, 433, conductor 434, winding of relay 501, armature 502 to the winding of the magnet M5. In this connection will be understood that the magnet M5 may be energized in a secondary or local circuit, in lieu of directly in the seriesed path traced; this also applying to magnets and relays in Fig. 4, for example. The wipers 431'-432' will now be moved from their normal position; wiper 431' remaining in contact with bar 425' while the wiper 432' will successively test the bank contacts engageable thereto until a grounded one is encountered. In view of the setting, this will be the first one engaged, corresponding to digit "1". Having in mind that the spring set 512 is continuously operated by cam 510 and that the springs of the said set 512 will disengage each other after wiper 432' moves off-normal and before it engages the next contact 411', it will appear that the operation of spring set 512 will cause a ground impulse to be applied through

armature 513 to the winding of relay 514. This will cause armature 500 to attract and deenergize relay 339 in the auxiliary selector AS3 for the duration of the closure of springs 512. 5 Relay 212 being energized in series with armature 340, this will cause relay 212 to retract and re-attract its armature and operate the vertical magnet VM2 to raise the wipers 241 to 243 one step into alignment with the first off-normal 10 level of bank contacts.

In view of bank contact 411' being grounded over the traced path, when wiper 432' engages it, a circuit path can be traced from ground on bank contact 411', wiper 431', bar 425', make- 15 before-break spring 515 to the winding of slow-releasing relay 516, the latter said relay actuating and locking to grounded off-normal spring 508. Armature 518 will ground conductor 337 to insure the armature 340 is maintained at- 20 tracted. The selector S2 will rotate-in at the first off-normal level and selectively seize the first idle set of bank contacts assumed to be 251 to 253 leading to selector T. Armature 520 will apply its ground over conductor 521 to the wind- 25 ing of stepping magnet SM'4 to operate it preparatory to advancing the set of wipers 425 to 429 upon its deenergizing. Armature 522 has no operative object at present due to relay 435 remaining inert because of its marginal char- 30 acteristic in view of the resistance in the digit conductor 1 being in the energizing path of relay 435. When the wipers 431' and 432' retract, the relay 516 will unlock consistent with its slow-releasing characteristic, the armature 500 35 having previously retracted. The magnet SM'4 will deenergize, causing wipers 425 to 429 to advance one step, wiper 425 then resting upon bank contact 450. A circuit path can now be traced from ground, winding of relay 435, spring 40 436, wiper 429, bank contact 451, wiper 412, bank contact 446, bank contact 450, wiper 425, armature 430 to the winding of stepping magnet SM'4. Relay 435 will not actuate, due to its marginal adjustment in view of the resistance of the wind- 45 ing of magnet SM'4, but the stepping magnet will interrupt itself and cause the wipers to be rotated an additional step, where a circuit will be closed including magnet SM'4, armature 430, wiper 425, bank contacts 452, 447, wiper 413, 50 bank contact 453, wiper 429, spring 436, winding of relay 435 to ground, causing the wipers 425 to 429 to be rotated an additional step, where a circuit path will be closed including magnet SM'4, armature 430, wiper 425, bank contacts 55 453, 448, wiper 414, bank contact 455, wiper 429, spring 436, winding of relay 435 to ground, causing the wipers to be rotated an additional step.

When the magnet M5 energized, wiper 404 was resting on bank contact 416. Wiper 405 was resting on bank contact 417 (which latter contact is tied to bank contact 419), and which latter condition caused the storing device to initiate its sending of impulses. It will become clear presently that bank contact 419 can be tied to any bank 60 contact engaged by wiper 405 to govern the initiating of the sending of impulses by the storing device consequent upon the completion of any numerical order of impulses sent from the calling line. In this connection, it will be noted that while the wipers 425 to 429 are being automatically rotated, the left-hand armature of the magnet SM'4 will operatively energize the slow-releasing relay 456 so it will maintain its armature 433 attracted to open the path extending to

magnet M5 during the time the wipers 425 to 429 are in the process of being rotated.

After the wipers 425 and 429 advance from bank contacts 454 and 455 respectively to the succeeding bank contact set, the magnet M5 will not energize to continue the advancement of the connection, unless during the time the digit "1" was being sent from the storing device and the wiper 425 was automatically advancing successively from bank contacts 450, 452 and 454, the calling party sent one or more of the last four (local) digits of the called telephone number wherein the switch DS4 will successively connect the wiper 404 to bank contacts 457 to 459, and wherein the digit setting elements A5, B5, C5 and D5 are caused to be successively set in accordance with the said four local digits sent from the calling line. For example, when the first (local) digit "2" is sent, the two impulses are applied through bank contact 416, conductor 460, winding of slow-releasing relay 525 to the stepping magnet 526, causing wipers 527 to 529 to be set upon bank contact 530 and bars 531 and 505 respectively. When the second digit "3" is sent, the three impulses are applied through bank contact 457, conductor 461, slow-releasing relay 532 to the stepping magnet 533, causing wipers 534 to 536 to be set upon bank contact 537 and bars 538 and 506 respectively. When the third digit "5" is sent, the five impulses are applied through bank contact 458, conductor 462, slow-releasing relay 539 to the stepping magnet 540, causing wipers 541 to 543 to be set upon bank contact 545 and bars 546 and 507 respectively. When the fourth (last) digit "3" is sent, the three impulses are applied through bank contact 459, conductor 463, slow-releasing relay 547 to the stepping magnet 548, causing wipers 549 to 551 to be set upon bank contact 552 and bars 553 and 508 respectively. The setting of the elements A5, B5, C5 and D5 to ground bars 531, 538, 546 and 553 in numerical order respectively, are made irrespective of directive impulses being automatically sent from the storing device. If any local digit has not been set-up, the sending by the storing device will stop when ready to send the unset local digit and will then automatically start sending upon the said digit being sent. In commercial operation, where the storing device will probably be set so as to start sending forthwith when the third prefix letter has been sent from the calling telephone, the calling party will usually have sent the remaining four local digits before the storing device is ready to start re-sending the said local digits, as the calling party will probably have had time to send the said local digits to the storing device during the time the interpreted trunking digits are being sent from the storing device by way of progressing the call to the office containing the called line.

After wipers 428—429 engage bank contacts 465—466 respectively, and ground from the armature of relay 525 is applied through wiper 528, bar 531, conductor 555 to bank contact 465, this ground will be continued over wiper 428, armatures 432—433, conductor 434 to magnet M5 to start the hunting operation of wipers 431'—432'. Ground on the wiper 429 derived through the winding of relay 435 will be applied to bank contact 466, conductor 467, resistance, wiper 527, bank contact 530 to bank contact 412', so that during the time wiper 432' is traveling to grounded bank contact 412' two openings of the energizing circuit of the line relay in selector T will occur at armature 340 to cause the wipers

of selector T to rotate-in at the second level to extend the connection to selector U. Upon relay 516 and the stepping magnet SM'4 thereafter deactuating in sequence in the manner set forth, the wipers 425 to 429 will advance an additional step so that wipers 428—429 engage bank contacts 468—469 respectively.

In this connection, it will be noted that due to the circuit path traced through wiper 527 and the winding of relay 435 including a resistance, the current derived through the winding of relay 435 will be restricted below the operative value thereof in view of its marginal adjustment. A similar condition will hold for each energization of relay 435 wherein wipers 534, 541 and 549 will be concerned in further descriptions. The resistances shown at the lower margin in Fig. 4 may manifestly be introduced contiguous to the bank contacts 411' to 420' in lieu of where drawer and thereby obviate the requirement of the introduction of the resistances in the respective paths of the wipers 427, 434, 441 and 449. Of course, the connection of any bank contact engaged by the latter said wipers and the bank contacts 411' to 420' may be such as to by-pass the latter referred to resistance in the manner as will appear presently with reference to bank contact 484.

If element B5 is set, ground from the armature of relay 532 will be applied over wiper 535, bar 538, conductor 556, bank contact 468, wiper 428, armatures 432—433, conductor 434 to the magnet M5 to start the testing operation of wipers 431'—432'. Ground on the wiper 429 derived through the winding of relay 435 will be applied to bank contact 469, conductor 470, resistance, wiper 534, bank contact 537 to bank contact 413', so that during the time wiper 432' is traveling to grounded bank contact 413', three openings of the energizing circuit of the line relay in selector U will occur at armature 340 to cause the wipers of selector U to rotate-in at the third level to extend the connection to connector V. Upon relay 516 and the stepping magnet SM'4 thereafter deactuating in sequence in the manner set forth, the wipers 425 to 429 will advance an additional step so that wipers 428—429 engage bank contacts 471—472 respectively. If element C5 is set, ground from the armature of relay 539 will be applied over wiper 542, bar 546, conductor 557, bank contact 470, wiper 428, armatures 432—433, conductor 434 to the magnet M5 to start the testing operation of the wipers 431'—432'. Ground on the wiper 429 derived through the winding of relay 435 will be applied to bank contact 472, conductor 473, resistance, wiper 541, bank contact 545 to bank contact 415', so that during the time wiper 432' is traveling to bank contact 415' five openings of the energizing circuit of the line relay in the connector V will occur at armature 340 to cause the wipers of connector V to be raised into alignment with the fifth level. Upon relay 516 and the stepping magnet SM'4 thereafter deactuating in sequence in the manner set forth, the wipers 425 to 429 will advance an additional step so that wipers 428—429 engage bank contacts 474—475 respectively. If element D5 is set, ground from the armature of relay 547 will be applied over wiper 550, bar 553, conductor 558, bank contact 473, wiper 428, armatures 432—433, conductor 434 to the magnet M5 to start the testing operation of wipers 431'—432'. Ground on the wiper 429 derived through the winding of relay 435 will be applied to bank contact 475, conductor 476, resistance, wiper 549, bank contact 552 to bank contact 413', so that during the time

wiper 432' is traveling to grounded bank contact 413', three openings of the energizing circuit of the line relay in connector V will occur at armature 340 to cause the wipers of connector V to be directly rotated-in to the third contact position and seize the terminals of the line leading to telephone TE in the well known manner of connectors in view of the citation. Upon relay 516 and the stepping magnet SM'4 thereafter deactuating in sequence in the manner set forth the wipers 425 to 429 will advance an additional step so that wipers 425—426 engage bank contacts 477—478 respectively; said bank contact 477 being permanently grounded. A circuit can now be traced from bank contact 477 wipers 425—426, bank contact 478, conductor 338, bank contact 334, wiper 324, armature 341, conductor 342, spring 229 to the winding of relay 230, the latter said relay actuating and locking to conductor 208. The latter said conductor is either grounded from the repeater interposed in the trunk leading to selector T, or from selector T if the so-called release trunk is carried back companion to the talking conductors. The auxiliary selector AS3 will restore, followed by the deactuation of relay 402 and the actuation of relay 440, in the manner described. Conductors 561 to 564 will ground bars 505 to 508 respectively, causing the corresponding stepping magnets to automatically operate to rotate the wipers engaged with the latter said bars off same and into the normal position shown in the drawings, after which relay 440 will deactivate to unguard the concerned storing device.

In this connection it will be noted that should the calling party, after sending all the digits, decide to abandon the call before the storing device has sent the interpreted impulses, he will replace the receiver, causing ground to be removed from conductor 208. This will cause the linking switches to be restored, as well as the auxiliary selector AS3, followed by relay 402. The restoring bars of the various elements attached to the armatures of relay 402 will cause the restoration of the elements which are off-normal, as described, as well as the operation of the release magnet Re4.

Assume that the call to telephone TE is made by calling the name prefix "Federal", followed by the four local digits "2353", in lieu of employing the three-letter prefix "FED" as in the last exemplified call. After initiating the call by removing the receiver, the finger-hole designated "Federal" (equivalent to digit "0") will be operated. This will cause the shaft of the auxiliary selector AS3 to be raised into alignment with the tenth ("0") level. The spring set 352 is designed to operate from the shaft cam 353 consequent to the shaft moving its wipers into alignment with the ninth level, so that when the grounded armature of relay 301 attracts after imparting the ninth ground impulse to the vertical magnet VM3 a circuit path can be traced from armature on relay 301, spring set 352 to the upper winding terminal of relay 339. Relay 339 will thus actuate and lock to grounded armature 355, so that when the armature on relay 301 retracts to apply the tenth impulse to the vertical magnet, a circuit can be traced from a branch of the impulse circuit traced for the vertical magnet VM3, through armature 356, conductor 353, winding of slow-releasing series relay 260 to the vertical magnet VM2 in first selector S2, causing the wipers 241 to 243 to be raised into alignment with

the first level and there rotate-in normally as if relay 212 had been actuated and then deactuated to impart an impulse to the vertical magnet VM2 in the well known manner, in view of the citation. The vertical magnet VM3 will operate normally in raising the shaft so the wipers 321 to 324 will align with the tenth level of bank contacts and there rotate-in in the manner before set forth, the wiper 324 engaging grounded bank contact 360. In this connection, it will be noted that the relay 339 will remain locked while either relay 301 or 310 remains actuated, and during the time relay 339 is actuated its armature 340 closes the before described energizing circuit for line relay 212, causing the latter said relay and the relay 219 to actuate and apply supplemental ground to conductor 208 before the last (tenth) impulse of the series is sent from the calling line.

The bank contacts coincidentally engaged by wipers 321 to 323 at the tenth bank level are unconnected. Having in mind that due to private wiper 321 not receiving ground from its engaged bank contact the relay 326 will actuate, a circuit path can thus be traced from grounded bank contact 360, wiper 324, armature 341, conductor 342, spring 229 to the winding of relay 230. Relay 230 will actuate and lock to conductor 208 now grounded through armature 221 as notwithstanding that relay 212 will deactuate consequent to the deactuation of relays 301 and 339 the relay 230 will actuate to cause relay 212 to become reenergized in series with the calling telephone CT to cause relay 219 to become re-energized before its armature 221 has had time to retract. Of course, if desired, to give a wider margin of adjustment whereby relay 339 will be held locked after relay 301 deactuates, the bank contact 361 engaged by wiper 323 may be grounded, and in that event the relay 212 will be maintained energized constantly after the closure of armature 340. The first selector S2 will function in the well known manner referred to to seize the first idle trunk in the first selector level, which will be assumed to be the one connected to the first set of bank contacts 251 to 253, as in the case last described wherein the storing device caused the said first selector S2 to operate through the agency of applying an open impulse to relay 212. The call is now extended to selector T from the calling telephone CT, from which point it can be directly directly extended to the called telephone TE by the calling party annexing the four local digits "2353".

Assume a call from the calling telephone CT to telephone TD, the telephone number of which is "DAIry—3457"; that is, by sending digits "321—3457" the call can be completed. It can also be completed alternatively by operating the dial finger-hole designated "Dairy" followed by digits "3457"; that is, by sending digits "7—3457". It will first be assumed that the three-letter prefix "DAI" (equivalent to digits "321") is sent, followed by local digits "3457". Responsive to sending the said three-letter prefix, the first selector S2, the auxiliary selector AS3 and the elements DS4, ND4 and SD4 will function as when the three-letter prefix "EDI" was sent, except in the present instance the wipers 411 and 414 will be raised three levels and set upon bank contacts 481 to 484 respectively. It will appear presently that the condition set-up consequent to the setting of wipers 411 to 414 upon bank contacts 481 to 484 respectively is that which will cause the digits "4672" to be sent successively

operative to selectors S2, N, O, P and the secondary non-numerical switch P', whereby the calling line will be progressed to local selector Q. In accordance with the sending of the last four (local) digits "3457" from the calling line, the same said digits will be re-sent by the storing device operative to selectors Q and R and connector S, as will appear presently. Attention is directed to the fact that due to the presence of the secondary switch P' in the connection, enough hunting time will be required as would be necessary for the selector P to selectively hunt over all the trunk positions of the second level and thereafter allow for the secondary switches thereof of which P' is one to hunt for an idle trunk leading to a selector of the group of the selector containing selector Q. As referred to at the outside in paragraph "n", it is objectionable to provide for such a delay at the termination of all digit series, so in the concerned call, the routing of which is specific to the prefix, an abnormally long period will be introduced between the third digit "2" resent and the following local digit "3" resent.

In view of previous descriptions it will be clear that the storing device is arranged for re-sending a train of four prefix series (from a train of three series) wherein the wipers 411 to 414 respectively correspond numerically to the numerical order of each said series resent, having in mind any of the said re-sent series may be omitted, though if an omission is to be made it will preferably (as exemplified) be those counting in numerical order including the first adapted to be sent.

When the wipers 411 to 414 are set upon bank contacts 481 to 484 respectively, the bank contacts 437, 451, 453 and 455 are tied to bank contacts 414', 416', 417' and 412', having in mind that an obstructing resistance is interposed between each set of said tied bank contacts, with the exception of the set of bank contacts 455—412', due to the by-pass from bank contact 484 to terminal 4d.

The general operation of the storing device is now clear in view of previous descriptions. Suf-
-fice it to state that the bank contacts 450, 452 and 454 will have no operative purpose in the present call, since in the present assumed call there are digits sent corresponding to the nu-
-merical position of the latter said bank contacts. That is, in the place of the wiper 425 being caused to automatically advance from each of the latter said bank contacts and thereby skip three numerical orders, the wiper 425 will only ad-
-vance from any bank contact other than the one it normally rests upon consequently to relay 516 actuating and thereafter deactuating consequent to a digit series being effectuated by the digit finder DF5. Thus, as the wiper 429 successively rests upon bank contacts 437, 451, 453 and 455, the bank contacts 414', 416', 417' and 412' (cor-
-responding to digits "4672") will become succes-
-sively grounded, effective to terminate the specific numerical impulse series being sent from arma-
-ture 500.

Having in mind that the calling party will most probably have sent one or more of the local digits before the fourth inter-office trunking digit has been sent from the storing device, it will be clear, in view of previous descriptions, that the first local digit and also the following three local digits will be consecutively annexed by the storing device. However, due to the fact there is a resistance included in the tie path between bank

contacts 455 and 412'', when the fourth inter-office trunking digit is being sent from armature 500 and the wiper 432' encounters bank contact 412', the path including the windings of relays 5 435 and 516 will not include an obstructing resistance, and under that condition the said marginally adjusted relay 435 will actuate and lock over conductor 480, armature 522 to grounded battery. When relay 516 deactuates, the relay 10 435 will be deenergized and wiper 429 will be advanced to bank contact 466 in the manner before described. But ground will be kept disconnected from the latter said wiper and also conductor 434 until relay 435 deactuates consistent with its said 15 slow release characteristic. Upon the retraction of armature 432 the before traced energizing path for the magnet M5 will be closed effective to initiating the sending of the first local digit series. Thus, the period between the fourth and fifth 20 digits in the assumed call sent from the storing device has been prolonged by the slow-release period of relay 435, providing for the maximum hunting time required by both selector P and the secondary switch E' assumed to be the first idle 25 secondary switch tested.

It is clear that while the relays 516 and 435 are shown as of the slugged type, a dash-pot or other slow-releasing type relay may be alternatively employed in lieu thereof or as a supplementary agency to maintain the path including conductor 434 open. When the last digit (eighth in the present exemplified call) has been sent and wipers 425—426 engage bank contacts 477—478 respectively, the relay 230 will be caused 35 to actuate and lock in the manner described, after which the relay 402 will deactuate to restore the various off-normal positioned elements of the storing device. The call has now been completed.

46 The feature of the storing device shown in Figs. 4 and 5 referred to as the outset in paragraph "7" operates as follows: When wiper 427 rests upon bank contact 489 (wiper 427 previously having no operative object) and when relay 516 is actuated due to wiper 432' finding ground on bank contact 415' a circuit path can be traced from grounded battery, wiper 427, bank contact 489, conductor 490, armatures 571, 572, winding of slow-releasing relay 573 to ground, relay 573 actuating. Grounded battery will be applied from armature 573 to the winding of relay 576, the latter said relay actuating and locking to battery through wiper 427. The energizing path to relay 573 will be opened after armature 575 attracts and energizes relay 576, but due to the slow-releasing characteristic of relay 573 armature 578 will not retract until wipers 431'—432' have had time to retract, whereupon a circuit path will ensue from alternating current generator G65, armatures 580, 578, bank contact 582, wipers 432'—431', bank contact 583, off-normal spring (not shown in Fig. 15) spring 507, spring 515 and through the winding of relay 516 to grounded battery. The said application of alternating current will cause the armatures of relay 516 to forthwith retract to start sending the last digit series. The sustaining period of relay 573 after its deenergization will be equal to or slightly longer than that of the series relay in connector, so that upon the said series relay deactuating and thereby placing the connector in readiness to operate its rotary magnet, the last series of impulses will thereafter be started from the storing device. That is, hunting time following

the operation of the connector in a primary direction will not be allowed for.

Assume that the figures are assembled as indicated in Fig. 25, and the call is made to telephone TD by calling the name prefix "Dairy", followed by the four local digits "3457" in lieu of employing the three-letter prefix "DAI" as in the last exemplified call. After initiating the call by removing the receiver, the dial finger-hole designated "Dairy" (equivalent to digit "7") will be operated. This will cause the wipers of the auxiliary selector AS3 to be raised into alignment with the seventh level and there rotate-in and select the first idle storing device assumed to be the one leading from the first set of bank contacts tested, though it will be understood the level will have a plurality of similar storing devices. In order to simplify the disclosure, Fig. 5 (companion to Fig. 4 in previous descriptions) is combined with Fig. 6 to disclose the storing device seized.

The parts concerned in the following description of Fig. 6 which corresponds to parts in Fig. 4 will be given the same numbers, but with "6" as an index digit in lieu of "4" as used in Fig. 4. Lines in Fig. 6 starting in Fig. 5 will have a prime added to the designation in Fig. 5.

Wipers 321 to 324 are now in engagement with bank contacts 362 to 365 respectively. Wiper 321 will apply ground to bank contacts 362 and its multiples to guard the seized storing device from intrusion by a selector companion to selector AS3, and also to apply the said ground over conductor 366, armature 601', make-before-break spring 602' to the winding of relay 603', the latter said relay actuating. It will be now noted that bank contacts 637, 651, 653 and 655 are tied through armatures 605', 606', 607' and 608' to bank contacts 414', 416', 417' and 412' respectively. Relay 339 is energized over a path including lower armature of relay 326, wiper 323, bank contact 364, conductors 367, 337 to grounded armature 500. A path can be traced from wiper 324, bank contact 365, conductor 368 to bank contact 673. Under the condition of relay 339 actuating, the relay 212 will actuate in the manner before described, so that the circuits are now prepared to transmit directive impulses from the storing device. The relay 602 is operatively energized in a local circuit of either relay 603' or 617', and is therefore now actuated, applying ground from armature 620' to bank contact 619 to cause the wipers 623 and 629 to rotate to bank contacts 631 and 637 respectively. The magnet M5 and relay 501 will be energized through wiper 628, armatures 632—633, conductors 634—434 to armature 502 and the element ND6 will function as before described to successively ground bank contacts 414', 416', 417' and 412', having in mind the excluded obstructive resistance in the circuit path energizing relay 635 when bank contact 412' is grounded and engaged by wiper 432'. That is to say, the storing device disclosed in Figs. 5 and 6 combined will forthwith automatically initiate the sending of digits "4672" upon its seizure, to progress the call through selectors S2, N, O, P and the secondary switch E' to selector Q where-in an abnormally long pause will occur before the first one of the impulses constituting the four local digits "3457" set-up by elements A5, B5, C5 and D5 will be started, assuming that the calling party annexed the said local digits, or the first one of them, before the fourth inter-office trunking digit "2" is sent from the storing device. After the fourth (last) local digit is sent by the storing

device bank contact 678 will be grounded from bank contact 677 to cause the actuation of relay 230.

- If it is desired to not have the sending from the 5 storing device initiate forthwith upon the relay 602 actuating, the bank contact 619 will be tied to bank contact 621' in lieu of to the make contact of armature 620', and under the alternative condition the sending from the storing device will 10 not be initiated until the termination of the first local digit series sent from the calling line. In view of the contacts beyond 621' being engaged successively for each local digit series sent from the calling line, it will be manifest that tying bank 15 contact 619 to any one of the off-normal bank contacts engaged by wiper 605 will correspondingly determine after what local digit series sent from the calling line the sending from the storing device will be initiated.
- 20 In this connection, it will be noted that the armatures 605' to 608' bear the same relation to bank contacts 637, 651, 653 and 655, and the respectively tied bank contacts 414', 416', 417' and 412' as did wipers 611 to 614 in the previous description when the latter said wipers were set upon bank contacts 481 to 484 respectively, to effect a call between the same telephones by the employment of a three-letter prefix in lieu of the present name prefix.
- 25 Assume a call from calling telephone CT to telephone TA, the telephone number of which is "FABer—6427"; that is, by sending digits "322—6427" the call can be completed. It can also be completed alternatively by operating the dial finger-hole designated "Faber", followed by digits "6427"; that is, by sending digits "7—6427". It 30 will first be assumed that the three-letter prefix "FAB" (equivalent to digits "322") is sent, followed by local digits "6427". The figures will be assembled as indicated in Fig. 24. Responsive to sending the said three-letter prefix, the auxiliary selector AS3 and the switches DS4, ND4 and SD4 and the first selector S2 will function as when the three-letter prefix "EDI" was sent, except 35 in the present instance the wipers 411 to 414 will be stepped-up three levels and set upon bank contacts 485 to 488 respectively. It will appear, presently, that the condition set-up consequent to the setting of wipers 411 to 414 upon bank contacts 485 to 488 respectively, is that which will 40 cause the digits "523" to be sent successively operative to selectors S2, B and C, whereby the calling line will be progressed to selector D. In accordance with sending the last four digits 45 "6427" from the calling line, the same said digits will be re-sent by the storing device operative to selectors D and E and connector F, as will appear presently.
- 45 When the wipers 411 to 414 are set upon bank contacts 485 to 488, the bank contacts 437, 451, 453 and 455 are tied to bank contacts 415', 412', 413' and 454, having in mind that an obstructing resistance is interposed between the first three pairs of said tied contacts.
- 50 The general operation of the storing device composed of Figs. 4 and 6 being now clear, suffice it to state that the contact 454 will have the operative purpose of causing the wipers 425 to 429 to automatically step from the bank position corresponding, so that wipers 428—429 will engage bank contacts 465—466 respectively. Having in mind that the calling party will perhaps have sent one or more of the (last four) local digits "6427" before the third inter-office trunking digit has been transmitted by the storing de-

vice, it will be clear, in view of previous descriptions, that the local digits will be consecutively annexed by the storing device, and when the last local digit has been sent, the relay 230 will be caused to actuate and lock and the various off-normal positioned elements of the storing device will be restored.

Assume that the figures are assembled as indicated in Fig. 25 and the call is made to telephone TA by calling the name prefix "Faber", followed by the four local digits "6427" in lieu of employing the three-letter prefix "FAB" as in the last exemplified call. After the calling party has initiated the call by removing the receiver of telephone CT the dial finger-hole designated "Faber" (equivalent to digit "8") will be operated. This will cause the shaft of the auxiliary selector AS3 to be raised into alignment with the eighth ("8") level, where it will rotate-in and select the first idle storing device, assumed to be the one leading from the first set of bank contacts tested.

Wipers 321 and 324 are now in engagement with bank contacts 371 to 374 respectively. Wiper 321 will apply ground to bank contact 371 (and its multiples) to guard the seized storing device from intrusion by a selector companion to AS3, and also to apply the said ground over conductor 376, armature 615', make-before-break contact 616' to the winding of relay 617'; the latter said relay actuating. It will now be noted that bank contacts 637, 651, 653 and 655 are tied through armatures 625', 626', 627' and 628' to bank contacts 415', 412', 413' and 654 respectively. Relay 339 is energized over a path including lower armature of relay 326, wiper 323, bank contact 373, conductors 367—337 to ground on armature 500. A path can be traced from wiper 324, bank contact 374, conductor 368 to bank contact 678. Under the condition of the relay 339 actuating, the relay 212 will actuate in the manner before described, so that the circuits are now prepared for automatically transmitting directive impulses from the storing device. The relay 602 being operatively energized in a local circuit of relay 617' is therefore actuated, applying ground from armature 620' to bank contact 619 to cause the wipers 628 and 629 to rotate to bank contacts 631 and 627 respectively. The magnet M5 will be energized through wiper 628, and the element ND6 will function as before described to successively ground bank contacts 415', 412', 413' and 654. That is to say, the storing device will forthwith automatically initiate the sending of digits "523" upon its seizure by auxiliary selector AS3 to progress the call through selectors S2, B and C to selector D. The local digits "6424" set-up by elements A5, B5, C5 and D5 will be forthwith sent from the storing device, assuming that the calling party annexed the said local digits, or the first one of them, before the third trunking digit "3" is sent from the storing device. After the fourth local digit is sent, bank contact 678 will be grounded from bank contact 677 to cause the actuation of relay 230 as before described.

In this connection, it will be noted that the armatures 625' to 628' bear the same respective relation to bank contacts 637, 651, 653 and 655, and the respectively tied bank contacts 415', 412', 413' and 654 as did wipers 611 to 614 in the previous description wherein the latter said wipers were set upon bank contacts 485 to 488 respectively, to effect a similar call from telephone CT to telephone TA by the employment of a

three-letter prefix in lieu of the name prefix used in the previous call.

Assume a call from calling telephone CT to telephone TB, the telephone number of which is "FADdist—2345". That is, by sending digits "323—2345" the call can be completed. The figures will be assembled as indicated in Fig. 24. Responsive to sending the three-letter prefix "FAD", the auxiliary selector AS3 will operate with relation to the third bank level, selecting the same storing device as before, assuming it to be idle, resultant to the said first digit, and thereafter set the wipers 411 to 414 upon bank contacts 491 to 494 respectively, resultant to the second and third digits. In view of previous descriptions this will tie bank contacts 437, 451, 453 and 455 to bank contacts 414', 418', 419' and 454 respectively, having in mind that the tie between bank contacts 451 and 418' does not include an obstructing resistance since bank contact 492 is tied to terminal 4e. The wiper 404 will now be resting upon bank contact 416 and the wipers 425 to 429 will have rotated one step off-normal due to wiper 405 applying its ground through contacts 417 and 419. The calling party may forthwith send the four local digits to set the elements A5, B5, C5 and D5 in order that no delay will occur in sending the local digits from the storing device following the set-up digits "489" (as interpreted from the three-letter prefix "FAD") from the storing device. Due to there being no obstructing resistance included in the path between bank contacts 451 and 418', the relay 435 will actuate at the termination of the second ("8") digit series of the inter-office trunking train to introduce an auxiliary pause for prolonging the normal pause at the termination of the said second series. This will allow the ample time for the secondary switch N' to seize the trunk leading to selector G, preparatory to extending the call to selector H responsive to the third set-up digit "9". The call will be progressed through selectors H, I and connector J to telephone TB responsive to the last four (local) digits being sent from the storing device.

Assume a call from calling telephone CT to telephone TC, the telephone number of the latter being "DECon—3345". That is, by sending digits "332—3345" the call can be completed. The figures will be assembled as indicated in Fig. 24 as in the last exemplified call. Responsive to sending the three-letter prefix "DEC" the auxiliary selector AS3 will operate with relation to the third bank level, selecting the storing device as in the last exemplified call resultant to the first digit, and thereafter set the wipers 411 to 414 upon bank contacts 495 to 498. In view of previous descriptions, this will tie bank contacts 337, 451, 453 and 455 to bank contacts 414', 416', 417' and 418' respectively. The calling party will now send the four local digits. In view of previous descriptions, it will be clear that the call will be completed by the storing device sending set-up digits "4678" interpreted from the three-letter prefix, followed by the four set-up local digits "3345", as primarily sent, completing the call through selectors S2, N, O, P, K, L and connector M to telephone TC. In this connection, attention is directed to the fact that the latter said call was progressed through selector O to selector P as in the call exemplified to telephone TD, but that in the said latter call the fifth digit (first local digit) series "3" was annexed with the normal pause period after the fourth (inter-office trunking) digit "8".

Reference has been made to prolonging the normal interval between directive impulse series to enable a selected secondary switch as PP' to hunt over a trunk group before the succeeding series is transmitted. This function will have application to an adaptation indicated in Fig. 30, wherein selector P" in said Fig. 30 is assumed as introduced into Fig. 21 where indicated by the dotted lines c21 and b21, displacing the selector P. In lieu of directly operating selector P with relation to the eighth level to select selector K, seizing the trunk repeater 301" (in Fig. 30) at the seventh level of selector O will cause selector P" to rotate-in selectively from normal position on its normal level and automatically test and select selector K. Thus, the operation of selector O with respect to the seventh level will serve to progress the call through selector P" to selector K in lieu of introducing the directive series to operate selector P step-by-step with relation to its eighth level. A prolonged pause will be introduced following the sending of the third series of seven impulses effective to selector O in order to allow for the latter said selector to operate with relation to the seventh level and the seized selector P" to thereafter automatically operate with relation to its normal level to select and seize the trunk terminating in selector K. This function of introducing an abnormally long pause after sending the third inter-office trunking series of seven impulses will be effectuated by excluding the obstructing resistance between the bank contact 453 in Fig. 4 and bank contact 417' in Fig. 5, for example. The repeater 301" and the selector P" may be of the type of repeater Fig. 21 and selector Fig. 18 in my pending U. S. application for patent Serial No. 171,637, filed May 29, 1917.

The storing device represented by Figs. 5 and 6 combined is adapted to function specific to the seventh and eighth levels depending upon what level it is seized from, there being a relay 603' specific to the seventh level and a relay 617' specific to the eighth level. Of course, by omitting parts not a function of operation with relation to the eighth level, for example, the storing device will become specific to the seventh level, and under such condition the seventh and eighth levels will be provided with specific storing devices. It will be noted that when either relay 603' or 617' operates, it disables the other of the said relays and also guards the storing device against being seized from the level corresponding to the disabled said relay, due to the grounding of spring 616' or 602', as the case may be.

The general plan of the present system contemplates that all offices, where possible, route calls over common trunk groups in the direction of any called line as far as possible, depending upon the geographical location of the calling and called offices in the system. For example, the trunk group shown between selectors B and C in Fig. 21 may serve an office or plurality of offices other than the one containing selector S2. However, a terminating selector (not shown) companion to selector B will serve to terminate each primary or secondary trunk from a said other office, the companion selectors having their bank terminals multiplied. Of course, if secondary non-numerical switches (not shown) are employed for any said selector companion to selector B, for example, the bank terminals of the said non-numerical switches will be correspondingly multiplied between their banks and the bank of selector B and its companion selectors of the

corresponding level extending to the group containing selector C.

Attention is called to the tone source T3 which applies a tone through armatures 381 and 382 to talking conductor 302 and to the calling party upon relay 303 actuating. This denotes the circuits are in readiness for starting the sending of the directive dial impulses. The tone is disconnected from the calling line consequent to the actuation of either relay 326 or relay 230.

The storing device indicated by Figs. 4 and 5 combined is specific to the third level by way of example. Other levels, as the second, fourth and fifth, for example, will have generally similar storing devices selectively accessible to the group containing selector AS3. However, the storing devices for the various levels will have the sets of bank contacts of the element corresponding to element SD4 wired specific to the trunk route to any called office indexed by the three prefix letters of the called line wherein it is remembered the first said letter will determine the level group of storing devices containing the one employed in the call and the second and third digits will be effective to operate the wipers of the element corresponding to the element SD4 coordinately to set them upon a set of bank contacts.

It will be manifest, in view of the foregoing descriptions, that a ten-thousand group or "office" may have two name prefixes, as where a change in prefix is being made and confusion might occur if calling well known telephone numbers having changed prefix were made impossible of direct completion. Under the changed prefix condition, assuming all the prefix letters are different in the changed number, a different level storing device will be attained depending upon the first prefix letter, but the connections to the setting bank contacts of the elements corresponding to SD4 relating to the last two letters of the prefix will correspond regardless of the numerical bank positions of the old and new bank contact set being different. That is, calling either three-letter prefix alternatively will cause the call to be progressed over the same trunk route to the ten-thousand group containing the called line. In this connection, it will also be manifest that certain thousands and hundreds groups of a ten-thousand group may be given independent prefixes, for convenience, looking to separating and perhaps expanding each latter said group as growth of the subscriber list warrants. This admits of using the same trunk group and route to a ten-thousand group while permitting different prefixes. Moreover, the numbers of the two (or more) prefix subscribers may be interspersed at random throughout the ten-thousand line terminal sets. Confusion in thus calling will be a remote possibility due to the fact widely different three-letter prefixes may be employed. At such time as it becomes advisable to segregate the lines into independent offices with respect to geographical location of subscribers, the trunk route for one or both offices will be changed by altering the connections to the bank terminals of the respective sets concerned on the elements corresponding to SD4 in the various offices of the system to conform to the changed trunk route.

It will be understood that the connections to the digit conductors of the various storing devices will preferably be temporary jumpers through convenient terminals, not shown, so that if a trunk route is to be changed, a convenient and definite means for altering the connections between the bank terminals (corresponding to those

in switch SD4, for example) or relay terminals (corresponding to those on relays 603' and 617' for example) is provided.

In foregoing circuit descriptions, the auxiliary selector AS3 was permanently companion to selector S2. This arrangement requires that for each first selector as S2, an auxiliary selector as AS3 must be provided, although the operative requirement of selector AS3 terminates when the switching relay as 230 actuates and locks. By assembling the figures as indicated in Fig. 27 so the lines extending to adjacent margins register, an organization is effected which admits of employing a less number of auxiliary selectors as AS3 than first selectors as S2. This is because of employing a finderswitch group wherein each finderswitch thereof forms an automatic flexible extender from an auxiliary selector to interlink an idle auxiliary selector with a trunk corresponding to a first selector as S2 which has been seized by a secondary lineswitch as SL consequent to the calling party initiating a call. After the extender has operated the corresponding auxiliary selector is in readiness to function in the manner described when permanently interlinked to a trunk corresponding to a first selector as S2.

Under the last foregoing assumed organization, if the calling party at telephone CT removes the receiver from the switchhook the connection will be automatically extended to trunk conductors 113, 202 and 208 in Fig. 2. The before traced path including the calling telephone CT can now be traced from conductor 113, spring 204, conductors 205, 801 to ground at armature 110 802 and from conductor 202, spring 201, conductors 302, 803, armature 804, lower winding of relay 805, common conductor 808, series winding of common relay 809 to grounded battery, relay 809 actuating to operatively energize relay 810. Relay 805 will attract its armature from its resting contact to its make contact and its armature 813 to its spring 814, but not disengaging spring 814 from its resting grounded contact due to a tensioning spring applied to 120 armature 804. This will cause ground to be applied through armature 813, conductors 816, 306, armature 207 to conductor 208 to maintain the relays 121 and 124 actuated. The armature 818 will apply ground to common conductors 819 and 125 820. All idle busy-test conductors of the finderswitches, as those attached to conductor 822, for example, will be grounded from conductor 820 through the armature corresponding to 812 of the relay corresponding to 805. In the case 130 of conductor 822, the ground will be applied through armature 823 of relay 824, since relay 824 corresponds to the set of bank contacts the wipers of finderswitch F8 are shown resting upon, there being a relay corresponding to 824 for each 135 set of bank contacts of the switch F8 wherein conductor 820 has a tap including its armature corresponding to 823 connected to the busy-test contacts of the corresponding bank contact set. There will be a plurality of finderswitches (F8 140 and F'8 only being shown) having access to a plurality of sets of commoned bank contact sets; three such sets being shown, one set not being wired.

Forthwith upon armature 818 attracting, a circuit path can be traced from ground, armature 818, conductor 819, armature 825 to the winding of slow-releasing relay 826, the latter relay actuating. A circuit can then be traced from ground, armature 828 to the lower winding ter- 145 150

5 minal of relay 829. A circuit path can be traced from the upper winding terminal of relay 829, armatures 831, 832, wiper 833, bank contact 834, conductor 836, armature 812 to upper winding 5 of relay 805. Had armature 812 been normal wherein the call emanated from the trunk corresponding to relay 824, the path traced to armature 812 would extend over conductor 820, armature 818 to ground, and under this condition 10 relay 829 will be short-circuited and the stepping magnet S'8 of finder switch F'8 will operate to advance its set of wipers one step, to be further advanced if wiper 835 there encounters ground. Under the condition existing, the 15 relay 829 will actuate, energized in series with magnet S'8, but magnet S'8 will not operate due to its marginal adjustment. Armature 832 will receive ground from armature 828 and apply it to fully energize relay 805 whereby its armature 20 804 will disengage its resting contact; its armature 802 will overcome the tension-spring thereon and disengage its ground contact and its armature 813 will overcome the tension-spring thereon and disengage the ground contact resting 25 on spring 814. Armature 835 applies ground received through armatures 828 and 832 over wiper 837, bank contact 838, conductor 816 before spring 814 disengaged from its resting grounded contact, so no lapse of ground occurs 30 to conductor 208. Conductors 801 and 803 will now be continued through bank contacts 841—842, wipers 843—844, armatures 845—846, conductors 847—848, conductors 205—302 in Fig. 3 to the ground and battery free terminals of relay 301, the latter said relay actuating, followed 35 by relay 303. Ground through armature 305, conductors 306, 850, will be applied through armatures 835 and 832 to sustain relay 829 before the relay 826 has had time to retract its armature 40 828, so no lapse of ground will occur to conductor 816. That is, conductor 816 now receives ground through armature 305 in auxiliary selector AS3. Relays 809 and 810 deactivate upon the upper winding of relay 805 energizing to 45 unbusy the finderswitch banks, having in mind that conductor 836 will be maintained grounded from conductor 850 and armature 835 to guard the trunk corresponding to selector S2 from intrusion by a hunting finderswitch. Conductor 50 213 in Fig. 2 will be continued over conductor 853, bank contact 854, wiper 855, conductor 857 to conductor 218 in Fig. 3. Conductor 217 in Fig. 2 will be continued over conductor 859, bank contact 860, wiper 861, conductor 862 to conductor 217 in Fig. 3. Conductor 342 in Fig. 2 will be continued over conductor 865, bank contact 866, wiper 867, conductor 868 to conductor 342 in Fig. 3. Conductor 358 in Fig. 2 will be continued over conductor 869, bank contact 870, 55 wiper 871, conductor 872, armature 873, conductor 874 to conductor 358 in Fig. 3. It is now clear that the auxiliary selector AS3 bears the same circuit relation with the trunk leading to selector S2 as when it was related permanently 60 thereto in lieu of through its companion finderswitch F'8 as in the present exemplified organization.

When the ground has been removed from conductor 306 under conditions as have been described, the relays 829 and 805 will deactivate, whereupon the finderswitch F'8 and the auxiliary selector AS3 are at normal. It will be noted, in this connection, that while relay 805 deactivates consequent to ground being removed from conductor 306, due, for example, to relay 230 actuating 65 and locking to conductor 208 in the manner described, the set of bank terminals accessible to the finderswitch corresponding will be guarded against seizure idly, due to armature 812 being retracted whereby busy-ground from conductor 820 will be applied to the busy bank contacts tied to conductor 836 upon any relay of the group containing relays 805 and 824 actuating.

The finderswitch F8 (and other finderswitches, not shown) is similar to the switch F'8 and has access to multiple sets of bank contacts commonly tied with corresponding bank contacts accessible to switch F'8. The conductor 878 will be tied to conductor 819 through armature 825 during the time relay 829 is actuated. So upon conductor 819 there becoming grounded, relay 879 will actuate, causing the stepping magnet S8 to rotate the wipers thereof to an idle set of bank contacts which will correspond to the trunk to which the calling line is extended, or which will cause the relay 880 to actuate if the said wipers are then resting upon the latter said set of bank contacts, in the manner described relating to switch F'8.

The conductors 881 to 887 leading downward 100 from the switch F8 correspond to similarly disposed conductors 857, 862, 847, 868, 848, 850 and 874 respectively in switch F'8 and lead to an auxiliary selector like AS3 (not shown) which, in common with said selector AS3 has access to 105 the same storing device at corresponding levels, though not necessarily at corresponding bank positions in the levels. A group of eight auxiliary selectors, such as AS3 and its respectively permanently companion finderswitch, such as F'8 may 110 serve twenty-five selectors such as S2, for example; each said selector having a relay corresponding 805 and a set of conductors each one of which is multiplied to a corresponding bank contact of a set independently accessible to each 115 finderswitch so that upon a call being initiated, the first idle finderswitch will operate to extend the connection to an auxiliary selector in a Y branch with a trunk corresponding to a first selector as S2.

Assembling the figures as represented by Fig. 26, having in mind that bank contacts of auxiliary selector AS3 are now wired as shown to the left of dotted line d9 in Fig. 9, the storing devices detailed in previous descriptions are combined 120 to form a universal storing device which may be seized at either the third, seventh or eighth level and thereby adapt the seized said storing device to the requirements of the level. As pointed out in paragraph "j" at the outset, thus organizing 125 the storing devices renders it possible to employ fewer storing devices than if specific level storing devices are used. Only a part of the element ND4 of Fig. 4 is shown in Fig. 9. Elements of switch ND4 of Fig. 4 indicated in Fig. 9 are to 130 be understood as related in Fig. 9 as in Fig. 4. The connections between Fig. 9 and Fig. 5 are to be understood as including not only the conductors shown and indicated, but those not shown and indicated which are shown in Fig. 4. 135 An extra wiper and cooperating bank contacts are added to element DS4 as employed in Fig. 9. Wiper 427 in Fig. 4 has no operative function in the present organization. Its object will appear presently.

Assume a call from telephone CT to telephone TD is made. The three-letter prefix being "DAI", a train of three two and one series of impulses will be sent from the calling telephone to effectuate the prefix. The first series will cause wipers 140

145

150

321 to 324 to be set upon bank contacts 331 to 334 respectively. Ground through armature 328 in Fig. 3 will be applied through armatures 901, 902 to the windings of relays 903 and 904, the latter said relay actuating. The attraction of the armatures 912 and 913 on relay 904 disconnects the windings of relays 603' and 617' from bank contacts 361 and 371 and applies ground to the said contacts respectively, to guard the storing device against seizure at the seventh and eighth levels by an auxiliary selector of the group containing AS3. The second series of two impulses will cause relay 403 to actuate and the vertical magnet VM4 to operate to raise the shaft carrying wipers 411 to 414 into alignment with the second bank level. The third series of one impulse will cause the relay 403 to again actuate and the rotary magnet RM4 to set the wipers 411 to 414 into engagement with bank contacts 481 to 484 respectively. The equivalent set condition exists between bank contacts 455, 453, 451, 437 and the bank contacts 414', 416', 417' and 412' as existed when a similar setting of wipers 411 to 414 occurred in Fig. 4. The four local digits sent from the calling telephone will cause the same set-up condition in Fig. 5 as in the call to the same telephone before described in relation to Figs. 4 and 5, noting that due to relay 903 being actuated the ground from wiper 405, bank contact 417 is applied through armature 905 to bank contact 419 to initiate the operation of element ND4 upon wiper 405 advancing to bank contact 417 at the termination of the third directive series sent from the calling telephone. The bank contacts 417 and 419 are permanently tied in Fig. 4. The connection will be extended under direction of the storing device Figs. 9 and 5 in the manner before described in relation to Figs. 4 and 5. The same general similarity of operation last described as between Figs. 4 and 5, and Figs. 9 and 5 would occur in case the cell had been to either telephone "FADdist-2345" or "FABer-6427". If the storing device represented in Figs. 9 and 5 is caused to be released by the auxiliary selector AS3 restoring in the manner described, the relay 440 will be maintained operated as long as ground is derived through it in restoring any of the off-normal positioned elements of the storing device. Armatures 902, 908 and 909 will now apply ground to bank contacts 371, 361 and 331 (and multiples) to guard the storing device against seizure during the time the off-normal positioned elements thereof are restoring.

Assume that the alternative five-series calling number "Dairy-3457" is sent from the calling line. The sending of the prefix will, as before described, cause the wipers 321 to 324 to be set upon seventh level bank contacts 362 to 365. The ground applied through wiper 321 will follow over bank contact 362, conductor 366, armatures 908, 912, spring 602' to the winding of relay 603', the latter said relay actuating. Relay 602 operating in a local circuit of each of relays 603' and 617' will now be actuated. Grounded armature 620 will operatively energize relay 915 to ground bank contact 931. Make-before-break spring 616' being attracted by its cooperating grounded armature, this ground will be applied through armatures 913, 909 and 376 to bank contact 371 to guard the storing device against intrusion. It will be now manifest that the armatures 605' to 608' have set-up the equivalent circuit relations as ensued upon wipers 411 to 414 being set upon bank contacts 481 to 484 respectively.

At the time relay 915 energizes from grounded armature 620 this ground is also applied through armature 905 to bank contact 419 to initiate the functioning of element ND4 and incidentally cause the stepping magnet SM4 to automatically function to step wiper 918 to bank contact 920, so when the calling party starts sending the four local digits of the called line number, the first series of impulses thereof will be applied through relay 403, wiper 404, bank contact 416, conductor 460 to set the element A5. The elements B5, C5 and D5 will be caused to be set in the manner before described. Upon the storing device being released by reason of auxiliary selector restoring in the manner described, relay 603' will deactivate, followed by relay 602, whereupon relay 440 will actuate and remain so for the object set forth until the off-normal positioned setting elements of the storing device restore.

Assume that the alternative five-series calling number "Faber-6427" is sent from the calling line. The sending of the prefix will, as before described, cause the wipers 321 to 324 to be set upon the eighth level bank contacts 371 to 374. The ground applied through wiper 321, bank contact 371, conductor 376, will be applied over armatures 909, 913, spring 616' to the winding of relay 617', the latter said relay actuating, followed by the actuation of relay 602. Grounded armature 620 will operatively energize relay 915 to ground bank contact 931. Make-before-break spring 602' being attracted by its grounded armature, this ground will be applied through armatures 912, 908 to bank contact 361 to guard the storing device against intrusion. It will be now manifest that the armatures 625' to 628' have set-up equivalent circuit relations as were set by wipers 411 to 414 being set upon bank contacts 485 to 488 respectively.

At the time relay 915 energizes from grounded armature 620, this ground is applied through armature 905 to bank contact 419 to initiate the functioning of element ND4 and incidentally cause the stepping magnet SM4 to automatically function to step wiper 918 to bank contact 920, so when the calling party starts sending the four local digits of the called number, the first series of impulses thereof will be applied through relay 403, wiper 404, bank contact 416, conductor 460 to set the element A5. The elements B5, C5 and D5 will be caused to be set in the manner before described. Upon the storing device being released by reason of the auxiliary selector AS3 restoring in the manner described, relay 617' will deactivate, followed by relay 602, whereupon relay 440 will actuate and remain so until the off-normal setting elements of the storing device restore.

It is clear that regardless of from what level the storing device shown in Figs. 9 and 5 is seized, the alternative bank contact sets of the concerned storing device in other accessible levels are barred against seizure. Also, that while the descriptions have referred to the grounding of bank contacts 371, 362 and 331 of the selector AS3 it will be understood that the multiplied bank contacts thereof accessible to other auxiliary selectors of the group containing selector AS3 are the contacts effective to guarding the storing device against intrusion.

The combination of the three levels (third, seventh and eighth) refer to the storing device shown in Figs. 9 and 5. It is manifest that the relay 617' and connections, for example, may be displaced, whereupon the eighth level will not then be concerned. In commercial operation the

alternative calling numbers will not generally refer to the same storing device as the prime calling numbers, as in the present exampled instance wherein the first letter in the two three-letter prefixes are respectively, "D" and "F", equivalent to digit "3". So the relays 603' and 617', or either of them, will be associated as set forth with the storing device or devices which are concerned in the corresponding three-letter prefixes of the primary calling number. Each of the storing devices of a level will be similarly wired; that is, preferably, though not necessarily. For example, the first and second sets of bank contacts of the seventh and eighth levels accessible to auxiliary selector AS3 may have individual storing devices like shown in Figs. 6 and 5 combined, while the first and second sets of bank contacts of the third level accessible to auxiliary selector AS3 may have individual storing devices like shown in Figs. 4 and 5 combined. Then, the third and following sets of bank contacts of the third, seventh and eighth levels may have combination storing devices as shown in Figs. 9 and 5 combined. The object of this possible arrangement is to enable the normal traffic to be handled by specific level storing devices and the over-flow traffic, which will not always concern all ten-thousand groups similarly, to be handled on universal storing devices.

30 Certain trunk routes from calling ten-thousand groups of the present contemplated system will be arranged as set forth in paragraph "o" at the outset. In carrying out this feature of the invention the selectors (inter-office) operated consequent to sending the called number prefix will be modified somewhat in detail to the said cited selectors. Refer to Fig. 12, which is a well known selector, in view of the citation at the outset wherein a device of the present invention is employed to operate a set of cam-springs thereof by the rotary movement of the wiper shaft after all the trunks of a specific level or levels have been tested. The cam 201' mounted on the wiper shaft has a projection 202' which operates the set of cam-springs LR after the wipers have tested all the trunk bank contact sets and found them busy and rotated off the last set. Normally, the leading-in trunk conductors 205' and 206' lead to the free terminals of the battery and ground windings of line relay 207' respectively. When the spring set LR operates, the relationship of the said leading-in trunk conductors and the said windings of relay 207' is reciprocated. However, it is preferred that the operation of the spring set LR be transient. That is, while the shaft is passing from the tenth connected trunk position to the eleventh dead position, assuming that the selector has a capacity of ten trunks per level. The object of the latter stated function wherein but a momentary reversal of battery flow from the windings of the line relay 207' over the trunk conductors is produced is to insure that under conditions of the call being progressed directly from the calling telephone finger-hole dial through the normal level or the first level of selector S2, there will not occur the possibility of falsely operating the service meter device associated with the talking path of the calling line should said motor device be operative only to a current reversal along the calling line of a duration longer than the said momentary one.

It will be understood that the selector S2 will have a set of cam-springs corresponding to the set LR in Fig. 12. In the latter instance, the said set will not necessarily operate at the nor-

mal level and the first level, as calls progressed over the said normal and first levels will possibly refer to calls to the calling or a contiguous office thereto wherein alternative trunk routes would ordinarily be of no avail nor object. In any event, calls progressed over trunks of the normal level of selector S2 will always be directly progressed from the finger-hole dial on the calling line. So there would be no requirement for adjusting the reversing cam-springs to operate on the said first level. Under this condition, the duration of reversals effected by inter-office trunking switches will have no effect on the meter device on the calling line, since the calling line is not then operatively in control of the called extension due to the storing device being interposed.

In applying a cam-spring set similar to LR to selector S2, the conductors 205' and 206' will correspond to conductors leading to armatures 213 and 214 respectively, and the relay 207' will correspond to relay 212. Other attachments to selector S2, as conductor 358, will remain as shown in Fig. 2. However, a further modification in selector S2 is made as shown in Fig. 11, 100 to be discussed presently. It is thus clear that in progressing a call to a remote ten-thousand group, the selectors S2, B, C, N, O, BB, CC and G will operate to momentarily reverse the direction of current flow projected back from their respective line relays when a said selector rotates off the last set of bank contacts at any level, excepting the referred-to normal level of selector S2.

It has been deemed expedient to have omitted 110 the disclosure of the features shown in Figs. 11 and 12 in foregoing descriptions, in as much as their object did not have any bearing on the descriptions and that the disclosure would be involved thereby. In view of the last foregoing 115 statements and descriptions to follow, it is thought the detailed operation of the said selectors S2, B, C, N, O, BB, CC and G and cooperating elements of the exampled system will be clear. It is to be remembered however, that the contemplated system exampled employs the foregoing described elements under the before assumed conditions. That is to say, all calling offices will not have alternative trunk routes to called offices, so the functions of reversing the 120 battery current flow if all the trunks of a level are found busy will not be required in such concerned levels of the selectors, nor will further adaptations of the described storing devices about to be discussed be required in such calling offices. 125

The modification of Figs. 2 and 3 disclosed in Fig. 11 and the modification of the various said inter-office selectors disclosed in Fig. 12, together with the storing device represented by Figs. 10 and 5 combined, in lieu of the storing device 130 represented by Figs. 9 and 5 combined, will be employed in the comprehensive embodiment. The operation of such system wherein calls are extended from calling telephone CT to telephones TD, TA and TC will be detailed, wherein calls to telephones TD and TC have alternative trunk routes which are automatically taken if a busy inter-office trunk group is encountered. The assembly of the concerned figures is shown in Fig. 26, having in mind that Fig. 10 is substituted for 135 Fig. 9. The automatic operation of the switches responsive to the removal of the receiver from the switch-hook of telephone CT and the setting of the auxiliary selector AS3 will be as described. The portion of the storing device shown in Fig. 140

10 is a modification of the portion shown in Fig. 9 in view of Figs. 4 and 6. The elements SD4 and ND4 are not shown in detail in Fig. 10, but certain elements thereof are indicated. Also, the 5 circuits in Fig. 9 interlinked with bank contacts 371, 362 and 331 and the relays 602, 903, 440 and 904 are omitted from Fig. 10, but understood to be operative as shown in Fig. 9.

Assume a call from telephone CT to telephone

- 10 TA. It will first be assumed that the three-letter prefix "FAB" is sent whereby the wipers 411 to 414 and 101' are set upon bank contact set 485 to 489 and 102' respectively, in the manner before described, the wipers 321 to 324 then 15 being set upon bank contact set 331 to 334 and wherein relays 903 and 904 will be actuated. Wiper 101' and bank contact 102' have no operative function in the present setting since there is no alternative trunk route provided in case all 20 trunks of any inter-office group is found busy. The circuit conditions ensuing are as described with relation to Fig. 9 in view of Fig. 4 for a similar call, so the complete operation will not need to be detailed to insure a clear understanding. 25 The same statement holds for a call from telephone CT to telephone TA wherein the name prefix "Faber" is employed in lieu of the three-letter prefix "FAB". The wipers 321 to 324 are in the latter instance set upon bank contacts 371 to 374 30 respectively, wherein relays 617', 602 and 915 will be actuated.

Assume a call from telephone CT to telephone TD. It will first be assumed that the three-letter prefix "DAI" is sent whereby the wipers 411 to 414 and 101' are set upon bank contact set 481 to 484 and 103' respectively, in the manner before described, the wipers 321 to 324 now being set upon bank contact set 331 to 334 and wherein 35 relays 903 and 904 are actuated. A circuit path 40 can be traced from bank contact 334, wiper 101', bank contact 103', upper winding of relay 105' to tied bank contacts 106' to 110' in the element ND4. Bank contacts 437, 451, 453 and 455 in element 45 ND4 are now tied through wipers 411 to 414 to bank contacts 491 to 484, armatures 112' to 115', digit conductors 4, 6, 7, 2 to bank contacts 414', 416', 417', 412' respectively, the obstructing resistance in digit conductor 2 not being included in the traced path through armature 115'. The 50 calling party will annex the four local digits to set the elements A5, B5, C5 and D5. The operative circuit condition will be as when a similar call was assumed made wherein Fig. 9 was concerned. However, in the present instance should 55 either selector S2, N, O or P encounter all trunks busy in the fourth, sixth, seventh and second levels respectively, the battery current projected back over the circuit extension from the windings of the line relay of the selector encountering the busy trunk group including the operative winding of the electro-polarized relay 385 in Fig. 3 (in view of Fig. 11) will be momentarily reversed. The inner electro-polarizing winding of relay 385 60 will be energized to conductor 306. The relay 385 will acuate under the reversed current condition, but not otherwise. Ground will be applied through armature 386 on relay 385, conductor 387, armature 262 on relay 230, upper off-normal spring set VR2 to the release magnet Re2, operative to restore the shaft of selector S2 and also succeeding selectors in case the selector which encountered the busy trunk group was succeedent to selector S2. Ground will coincidently be applied through armature 388 on relay 385, armature

341, wiper 324, bank contact 334, conductor 333, wiper 101', bank contact 103', upper winding of relay 105' to bank contacts 106' to 110'. Having in mind that wiper 405 in element DS4 will engage bank contact 417 forthwith following the 80 said setting of the wipers 411 to 414 and 101', wiper 427 in element ND4 will become resting upon one of the contacts 106' to 110', applying grounded battery thereto. It is thus manifest the relay 105' in Fig. 10 will energize and actuate, 85 its lower winding locking through armature 116' to the conductor attached to bank contact 331, the latter conductor being grounded from armature 323 in auxiliary selector AS3. Armature 117' (on relay 105' in Fig. 10) applies its ground through armature 118' to the winding of slow-releasing relay 119', the latter relay actuating. Ground from said armature 117' is also applied through armatures 118', 122', bar 442 in element 90 ND4, wiper 426, armature 430 on stepping magnet SM'4 to the winding of the latter said magnet. The latter said magnet will automatically function to rotate the wipers 425 to 429 so wipers 425 and 426 will engage bank contacts 477 and 478 respectively. Due to wipers 425 and 426 being 100 tied, ground on bank contact 477 will cause the wiper 425 to automatically rotate therefrom to the normal position shown in the drawings. Due to armature 125' being attracted, the ground applied to bank contact 478 when wiper 425 engages bank contact 477 will not now be applied through wiper 324, to cause either relay 230 or relay 227 in Fig. 2 to actuate, as occurred in previous descriptions. On the other hand, the ground received 105 from bank contact 478 will be applied through armature 125' to the winding of relay 126', causing the latter said relay to actuate and lock to the grounded conductor leading to bank contact 331. Having in mind that relay 456 remains actuated while stepping magnet SM'4 is operating, the 110 magnet M5 will be disabled upon ground being applied to bar 442 so that it will not be enabled to energize to cause impulses to be transmitted from armature 500 until the armature 433 on relay 456 retracts, its period after the wipers 425 to 429 have been returned to the normal position shown 115 in the drawings. When the wipers 425 to 429 have been returned to normal position, a circuit path can be traced from grounded armature 117', 120 armatures 121', 128' to bank contact 419 in element ND4 during the time armature 128' sustains, 125 which will be until after wiper 426 returns and normally engages bank contact 419. The latter function serves to re-initiate the functioning of element ND4. The wiper 427 will not now be 130 enabled to complete a circuit path to ground over the path including bank contact 334, since the relay 385 in selector AS3 will deactivate forthwith upon the selector S2 retracting its wipers. Due to armature 121' being attracted, the false ground 135 is removed from bar 442, so when relay 456 retracts its armature 433 the circuits are in readiness to energize magnet M5 in a path including bank contact 437 for again automatically transmitting directive impulses from the armature 500 in Fig. 5 as before, but consistent with the alternative trunk route, as will appear. However, in view of the fact relay 105' is actuated and locked the bank contacts 481 to 484 and 103' are 140 now tied to bank contacts 415', 412', 412' and 412' in lieu of bank contacts 414', 416', 417' and 412' respectively. That is, the three-letter prefix "DAI" will be interpreted into inter-office trunking digits "5222" in lieu of digits "4672" primarily 145 150

interpreted by the setting of the wipers 411 to 414 and 101' upon bank contacts 481 to 484 respectively. It will be noted that the path including armature 115', terminal 4d to bank contact 412' does not include the obstructing resistance whereas the present path including the armature 114' and bank contact 412' does, for the object now clearly understood. It is, of course, manifest that the make contacts respectively engaged by the armatures 112' to 115' may from time to time be connected to other digit conductors than shown, in case the primary or the alternative trunk route (or both routes) to the office containing the called line leading to telephone TD is changed. Moreover, the said make contacts cooperative with armatures 112' to 115' respectively, may attach to digit conductors which will direct the call to a telephone irrelevant to the one called by the calling party; the information or complaint switchboard (not shown) for example. So if a group of trunks are tested over and found busy, the call will be directed to an attendant who will explain the condition to the calling party. With the latter mentioned arrangement there may not be an alternative route. The busy trunk condition encountered may have been due to a shortage of trunks for the ensuing traffic, or the test terminals of the trunks of the group may have been falsely busied by office attendants due to an out-of-order condition of the trunks, as from a cable failure, for example.

With further reference to the actuation of relay 105' in Fig. 10 and the false restoration of the element ND4 described, upon a busy trunk group being encountered, it will be noted that the operation of the element DS4 has not been affected, so that if the calling party is sending the series corresponding to any of the four local digits of the called line, the setting of the elements A5, B5, C5 and D5 will proceed normally irrespective of the functioning initiated by the actuation of the electro-polarized relay 385 in auxiliary selector AS3.

The storing device will now transmit the digit series whereby the selector S2 will again operate; this time to the fifth level (in lieu of the fourth level) and select an idle trunk to selector B. The call will be progressed through the levels of selectors C, PP (as indexed by the present setting of the storing device), secondary switch PP' to selector Q. The selectors P and PP and the secondary switches P' and PP' have their corresponding bank contacts multiply tied respectively. The trunks of the second level of selector C which each terminate in a selector in the group containing selector PP may be normal inter-office trunks between the switching center containing selector C and the switching center containing selector PP primarily used in calls to the office containing terminals of the line leading to telephone TD from another office or offices than the office containing lineswitch LS in Fig. 1. When the call has been completed to the called line consequent to the sending of the last digit series corresponding to the last local digit, the ground on bank contact 477 will be applied through wipers 425—426, bank contact 478, conductor 338, bank contact 334, wiper 324, armatures 341, 388, spring 229 to the winding of relay 230, causing the latter relay to actuate and lock to conductor 203 and to disconnect and restore the auxiliary selector AS3 as has been described. This removes the ground from bank contact 331, causing the restoration of the storing device.

It will be assumed that the call to telephone TD is made by the calling party operating the finger-hole dial with reference to the name prefix "Dairy", followed by the four local digits. In view of Fig. 9, and previous descriptions, the wipers 321 to 324 will be set upon bank contacts 362 to 365 respectively, and wherein relays 603', 602 and 915 will be actuated and wiper 918 will automatically advance to bank contact 920. Having in mind that wipers 411 to 414 and 101' are permanently tied to armatures 605' to 608' respectively, it will be manifest that the equivalent circuit relations exist in the storing device as when the latter said wipers were set upon bank contacts 481 to 484 and 103' respectively. Due to the attracted state of armature 620, bank contact 419 will apply ground to wiper 426 in element ND4 to initiate the operation of the latter said element, after which it will function as before described in normally progressing the call through inter-office selectors S2, N, O, P, having in mind that due to the wiper 404 in element DS4 now resting on bank contact 416, the next digit (first local) series sent from the calling line will set the element A5 correspondingly. The succeeding local digit series will set the elements E5, C5 and D5 in corresponding successive order, regardless of the functioning of element ND4 wherein it will be restored to normal and automatically initiate its functioning consequent to a ground being applied from armature 388 in the auxiliary selector AS3, in the manner about to be described.

It will be assumed that one of the inter-office selectors S2, N, O or P fails to find an idle trunk 110 in the level it rotates-in at and therefore operates its cam-springs corresponding to LR in Fig. 12 to reverse the battery projected towards the calling end including the operating winding of electro-polarized relay 385 and armature 340, 115 whereupon the armature 388 will apply ground through wiper 324, bank contacts 364, armature 135', upper winding of relay 105' to bank contacts 106' to 110' and armature 386 will cause selector S2 to restore as described. The wiper 427 120 will be resting upon one of said contacts 106' to 110', so that the traced path will be completed through the grounded battery attached to wiper 427. Relay 105' will actuate and lock in the manner before described, followed by relay 119' 125 actuating and the grounding of bar 442. The element ND4 will thus function as when relay 105' actuated in a foregoing description, followed by a new progression of the call over the same alternative route as in the latter said foregoing 130 description. That is to say, regardless of which prefix is employed in the call to telephone TD (the one employing the one impulse series corresponding to the name), or the one employing the three impulse series corresponding to letters, the 135 functioning of the inter-office selectors in the normal and the alternative routes will be the same.

Assume a call from calling telephone CT to telephone TC. Consequent to sending the three-letter prefix "DEA", the wipers 411 to 414 and 101' will be caused to be set upon bank contacts 495 to 498 and 137'. Bank contacts 437, 451, 453 and 455 in element ND4 are now tied through wipers 411 to 414, bank contacts 495 to 498, armatures 139' to 142', digit conductors 4, 6, 7, 8 to bank contacts 414', 416', 417', 418' respectively. The calling party will annex the four local digits to set the elements A5, B5, C5 and D5. The operative circuit conditions will be as when a similar 150

call was assumed made wherein Fig. 4 was concerned, in view of Fig. 9. However, in the present instance, should either selector S2, N, O and P encounter all trunks busy in the level it rotates-
5 in at, and therefore operates its cam-springs corresponding to LR in Fig. 12 to reverse the battery projected towards the calling end including the operating winding of electro-polarized relay 385 and armature 340. The armature 388 will apply
10 ground through wiper 324, bank contact 365, wiper 101', bank contact 137', lower winding of relay 145' to bank contacts 106' to 110' and armature 386, which will cause selector S2 to restore as de-
15 scribed. The wiper 427 will be resting upon one of said contacts 106' to 110' due to wiper 405 having applied its ground to bank contact 417 to ini-
20 tiate the operation of element ND4, so the traced path will be completed through grounded battery attached to wiper 427. Relay 145' will actuate
25 and lock through armature 146' to the conductor leading to bank contact 331, followed by relay 119' actuating from ground received from armature 148', and the grounding of bar 442. The ele-
30 ment ND4 will thus function as when relay 105' actuated in foregoing descriptions, followed by a new progression of the call over the alternative route indexed by the changed setting effected by relay 145' wherein armatures 139' to 142' now at-
35 tach to bank contacts 415', 412', 412' and 418'
40 in lieu of bank contacts 414', 416', 417' and 418' respectively. This will mean that the prefix "DEA" will be alternatively interpreted as digits "5228" in lieu of "4678" as primarily. The alter-
45 native route will thus include the fifth level of se-
50 lector S2, second level of selector B, second level of selector C and the eighth level of selector PP. The four local digits, as in all cases where alter-
55 native routes are taken, will be annexed normally, since the restoring and reinitiation of the func-
60 tioning of element ND4 occurs before any of the stored local digits have been sent by the storing device, and moreover, the local digits definitely determine the numerical location of the called line in the containing ten-thousand group. At
65 the termination of the last digit series, ground will be applied to bank contact 478, effective to ac-
70 tuate and lock relay 230 and restore auxiliary selector AS3. This ungrounds bank contact 331 and deenergizes the actuated relays, so the stor-
75 ing device will restore.

The means for automatically effecting a connection over an alternative trunk route disclosed in foregoing descriptions contemplates that calls from the concerned calling office to two ten-thousand groups have alternative trunk routes; there being one alternative trunk route in each instance, or as stated, the calling line may be ex-
80 tended to a switchboard (over well known equipment elements, not shown) from selector S2, in the event any group of inter-office trunks of the normal route are found all busy. A relay, as 105' and 145', is provided specific to each alternative connection. It will be manifest that additional relays, similar to relays 105' and 145' can be asso-
85 ciated with as many sets of bank contacts of the element SD4 as is desired. They will be introduced, as are the latter two said relays, with due regard to the alternative call connection to be made.

70 In this connection, it will be understood that the alternative call connection may constitute more than four digit trains described. That is to say, for example, the relay 145' may have four armatures 161', 162', 163' and 164' added as shown in Fig. 29. The conductors leading from

bank contacts 466, 469, 472 and 475 in element ND4 will lead to the said armatures respectively, and be continued through the respective resting contacts thereof through the resistances to wipers 527, 534, 541, and 549 respectively, in Fig. 5, in lieu of leading directly thereto from the said bank contacts as has been described. The make contacts of the said added armatures 161' to 164' will be connected to the digit conductors leading to the bank contacts of element DF5 in accordance with the route the alternative call connec-
80 tion is to take. So it is clear that in the case of the described call to telephone TC, for example, if a busy inter-office trunk condition is encountered wherein relay 145' will be caused to actuate and lock and the element ND4 restores and automatically re-initiates its functioning, that a complete, new eight-digit connection will be alternatively made. If it is assumed that the make contacts cooperative with armatures 161' to 164' lead to digit conductors 3, 4, 5 and 6 in Fig. 10 respec-
85 tively, the call will not only take the alternative trunk route originally described, but the call will be progressed to the line terminals "3456" in the ten-thousand group containing telephone TC. Of course, it will be understood that the make contacts cooperative with armatures 139' to 142' and 161' to 164' may be attached to other digit conductors than shown in Figs. 10 and 29, and in that event, the call will be correspondingly progressed upon the actuation of relay 145'. The latter referred-to attachments may concern the progression of the call to a set of line terminals in any ten-thousand group; in fact, to the group containing the calling line.

110 In the offices of the system located favorably to the employment of alternative trunk routes to a large plurality of the other offices of the system, the employment of an individual relay in each storing device concerned in such calls may introduce an objectionable multiplicity of such relays as 145' in Fig. 10. In that event, the disposition of the equipments of such concerned storing devices will be as set forth in Figs. 17, 18 and 19, about to be described. The general plan of alternative routing disclosed in the latter said Figs. is to initially coincidentally set-up a plurality of inter-office route (or other alternative extensions to telephone lines or switchboards) stored conditions having an order of preference, and then progressing the call in the direction of the called line (or alternative called line or switchboard) over the routes successively until an inter-office route is found having idle trunks, which of course, may be the primary or first pre-ferred route.

115 Figs. 17 and 18 assembled with other figures as indicated in Fig. 28 provides for one alternative trunk route for each bank position of the wiper set 411 to 414 of element SD4. The elements of the present discussed storing device are as indicated, having in mind the Figs. 4, 6, 9 and 10, of which it is a modification.

120 In the descriptions about to be entered upon, the bank contacts of auxiliary selector AS3 are wired as shown to the left of the dotted line d9 in Fig. 9. The relays 403, 915, 449, 904, 602, 903, 603', 617', 105' and elements ND4 and DS4, not shown wired in Fig. 17 are to be assumed incorporated, wired as assumed in Fig. 10.

125 The storing device disclosed in Figs. 17, 18, 19 and 5 combined is of the said universal type in that it may be seized from either the third, seventh or eighth bank levels of auxiliary selector AS3 as in the described case of Figs. 10 and 5

combined. The armature 135' on relay 603' has the normally closed contacts of the shaft off-normal spring set ON4' (which is companion to spring set ON4 shown in Fig. 4) introduced in 5 the tie to the conductor leading to bank contact

334. With the latter statements in mind, it is 10 though that the operation of the storing device with relation to the seventh and eighth levels of auxiliary selector AS3 will be clear without further reference, in view of the descriptions relating to Fig. 10. It will be noted, however, that the relay 105' has no wired relation to the bank contacts 481 to 484 in the present adaptation, since the relay 105' is specific to calls wherein the 15 storing device is seized at the seventh level.

The wipers 411 to 414 are normally tied through the armatures of relay 701' to bank contacts 437, 451, 453 and 455 respectively, so the 20 relation of the said wipers and bank contacts are normally as in Figs. 4, 9 and 10. The shaft 25 703' carries auxiliary wiper sets 805' to 808' and 810' to 813'. That is, when the set of wipers 411 to 414 is set upon a set of bank contacts, the other said auxiliary wiper sets are coincidentally set upon correspondingly located bank contact sets.

The wiper sets 805' to 808' and 810' to 813' refer 30 to alternative inter-office trunk routes, wherein if the call cannot be completed over the route indexed by the setting of the wiper set 411 to 414 due to encountering all trunks of a concerned group busy, the progressed call will be automatically destroyed and automatically re-routed over the route indexed by the setting of the wiper set 35 805' to 808'. And if the call cannot be completed over the latter said route, due to encountering all trunks of a concerned group busy, the last progressed call will be automatically destroyed and automatically re-routed over the route indexed by the setting of the wiper set 40 810' to 813'. The circuit scheme in Fig. 17 does not concern the latter said set of wipers; these are concerned in the modification of Figs. 17 and 18 indicated in Fig. 19.

45 It will be understood that while the said wiper sets in Figs. 17 and 18 are shown companion of the same drive-shaft, they may be mounted on separate drive-shafts 703', 901' and 902' shown in Fig. 19. Under this latter condition each of 50 the plurality of said drive-shafts will be independently operated by an individual set of vertical, rotary and release magnets (not shown), preferably, but of course, not necessarily connected in multiple relation with the windings of 55 magnets VM4, RM4 and RC4 respectively. Thus, the installation may initially be provided with a storing device like shown in Figs. 10 and 5, and at a future time be modified by the addition of the said supplemental shafts and wiper sets. It 60 will also be understood that in lieu of the storing device being of the universal type referred to, reached from a plurality of bank levels of auxiliary selector AS3, the relays 603', 617' and 105' and pertinent connections may be dispensed 65 with, whereupon it will relate solely to the third bank level of the latter said auxiliary selector group.

70 Assume a call from telephone CT to telephone TD wherein the three-letter prefix "DAI" is sent whereby the wipers 321 to 324 of auxiliary selector AS3 are set upon bank contacts 331 to 334 respectively, and the wipers 411 to 414 are set upon bank contacts 481 to 484 respectively; 805' to 808' are set upon bank contacts 815' to 818' respectively and wipers 810' to 813' are set upon

bank contacts 820' to 823' respectively. That is to say, the present operative circuit condition set-up in the storing device is equivalent to the condition set-up when Fig. 10 was concerned in a similar call.

80 Assume selectors S2, N, O and P incorporate spring sets as LR in Fig. 12, and that auxiliary selector AS3 incorporates the pertinent elements of Fig. 11. It will be clear that if any of the said selectors S2, N, O and P fails to find an idle trunk in the level it operates on, ground will be applied over bank contact 334 from armature 338. This ground will be applied through make off-normal spring set ON4', upper winding of relay 701' to bank contacts 106' to 110' in element ND4. In view of previous descriptions, wiper 427 will be included in the latter traced path, so the relay 701' will actuate and lock its lower winding through its armature 706' to ground through bank contact 331. The selector 85 S2 will be restored in the manner described, due to the actuation of relay 335. Ground will be applied through armature 708' to operatively energize relay 119' and to ground bar 442; the latter to cause the restoration of element 90 ND4 in the manner as set forth in previous descriptions. When bank contact 478 in element 95 ND4 has ground applied to it, relay 126' will actuate and lock to ground through bank contact 331, and ground from armature 708' will then be applied through armatures 121' and 128' to bank contact 419 to re-initiate the functioning of element ND4 in the manner before described. The lower armatures of relay 701' being attracted, the bank contacts 437, 451, 453 and 454 are connected over conductors 710' to 100 713' to wipers 805' to 808' respectively. The bank contacts 437, 451, 453 and 455 are now tied to bank contacts 415', 412', 412' and 412' respectively, the digit "2" conductor having its 105 resistance by-passed to terminal 4d in the tie path between bank contacts 484 and 412' and between bank contacts 818' and 412' for the object before referred to. The call will now be 110 progressed over the alternative route including 115 selectors S2, B, C, PP, secondary lineswitch PP' to selector Q, as before described in a like call wherein Fig. 10 was concerned.

120 Assume the modification of Figs. 17 and 18 by the introduction of Fig. 19. It will be clear 125 that a second alternative route is available in case the first alternative route presents a busy trunk condition, causing relay 335 in Fig. 3 to again actuate to restore the shaft of selector S2 and apply ground through bank contact 334. Having in mind that relay 126' is locked and relay 119' is normal, the ground path may be traced from bank contact 334 make contact of off-normal spring set ON4', armature 903', upper winding of relay 904', bank contacts 106' to 110' in element ND4, wiper 427 to grounded battery, the relay 904' actuating and locking its lower winding through armature 905' to grounded bank contact 331, ground will be applied through armatures 906', 907' to the winding of slow-releasing relay 908', the latter said relay actuating. The latter said ground will also be applied through armature 910' to bar 442 to again cause the restoration of the element 130 ND4. When ground is again applied to bank contact 478, this ground will be applied through armatures 125', 915' to the winding of relay 916', the latter said relay actuating and locking to ground through bank contact 331, and ground from armature 906' will then be applied 135 through armature 910' to bar 442 to again cause the restoration of the element ND4. When ground is again applied to bank contact 478, this ground will be applied through armatures 125', 915' to the winding of relay 916', the latter said relay actuating and locking to ground through bank contact 331, and ground from armature 906' will then be applied 140 through armature 910' to bar 442 to again cause the restoration of the element ND4. When ground is again applied to bank contact 478, this ground will be applied through armatures 125', 915' to the winding of relay 916', the latter said relay actuating and locking to ground through bank contact 331, and ground from armature 906' will then be applied 145 through armature 910' to bar 442 to again cause the restoration of the element ND4. When ground is again applied to bank contact 478, this ground will be applied through armatures 125', 915' to the winding of relay 916', the latter said relay actuating and locking to ground through bank contact 331, and ground from armature 906' will then be applied 150 through armature 910' to bar 442 to again cause the restoration of the element ND4.

plied through armatures 907' to bank contact 419 to re-initiate the functioning of element ND4 in the manner before described. The lower armatures of relay 904' being attracted, the 5 bank contacts 437, 451, 453 and 455 are continued over conductors 921' to 924', wipers 810' to 813', bank contacts 820' to 823' to bank contacts 412', 414', 417' and 454 respectively. The 10 call will now be alternatively progressed over the route including the second level of selector S2, fourth level of selector BB, seventh level of selector CC to selector DD. The latter said selector is companion to selector Q and is therefore an inter-office trunk terminating local selector (or so-called incoming selector) in the 15 ten-thousand group containing the called line terminals. The four local digits of the called line will be sent from the storing device forthwith, provided they have been set-up in the elements A5, B5, C5 and D5 responsive to the calling party having operated the finger-hole dial in accordance with the last four digits of the called line, having in mind that the setting of the latter said elements is not affected by the 20 busy trunk conditions encountered. The calling party will therefore not be aware of the re-routing of the call after it has been partly progressed towards the called line terminals. This latter statement also applies to previous descriptions wherein an alternative route was taken 25 after automatically destroying a partly established connection over the normal inter-office trunk route.

The relays 701' and 904' are not specific to 30 any one set of bank contacts as relays 105' and 145' wherein they were individual to bank contact sets 481 to 484 and 103', and 495 to 498 and 157' respectively, in Fig. 19. The relays 701' and 904' will operate under like conditions 35 with respect to any sets of bank contacts the wiper sets shown in Figs. 17, 18 and 19 are coincidentally set upon.

It is not thought necessary to a full understanding of the operation of the storing device incorporated in Figs. 17, 18 and 19 and cooperative figures to detail calls wherein the wiper set 411 to 414 is set upon bank contacts 485 to 488 respectively, to effect a call to telephone TA wherein wiper set 805' to 808' is coincidentally set upon 40 bank contact set 831' to 824' and wiper set 810' to 813' is coincidentally set upon bank contact set 841' to 844' respectively. The normal route will be as before described, while the first and second preferred alternative routes will be consistent 45 with the set-up inter-office trunking digits "532" and "8709" respectively. In the same manner, if wiper set 411 to 414 is set upon bank contacts 495 to 498 respectively, to effect a call to telephone TC wherein wiper set 805' to 808' is coincidentally set upon bank contact set 845' to 848' and wiper set 810' to 813' is coincidentally 50 set upon bank contact set 851' to 854' respectively, the normal route will be as before described, while the first and second preferred alternative routes will be consistent with the set-up inter-office trunking digits "5228" and "7649" respectively. In this connection, it will be understood that the said second alternative route 55 may refer to a called switchboard or other station at which an attendant will respond to inform the calling party of the condition encountered. The switches concerned in the latter will include selector S2 and other switches shown in Fig. 21 consistent with the route, and other well 60 known apparatus, not shown. It will, of course,

be manifest that in lieu of progressing the connection to an attendant's switchboard after destroying the futile connection attempted over the primary and first preferred alternative trunk routes when busy trunk conditions are encountered, it may be extended to a tone source so that the calling party will be apprised of the condition. For example, the connection may be progressed through the fifth level of selector S2 and the third level of selector B to a selector similar to selector B, not shown, wherein a ground-seeking tone source is applied to the talking path between the two latter said selectors. 65

It will be noted that due to the shaft off-normal spring set ON4' being as drawn when the wiper shaft 903' is at normal, the upper winding of relay 701' is disabled while the upper winding of relay 105' is operatively related through armature 135' to bank contact 334. Thus, if ground is applied to bank contact 334 while wiper 427 is resting on one of bank contacts 106' to 110', which relay, 701' or 105' will actuate will depend upon the state of the wiper shaft 703' and the state of relay 603'. That is, if the storing device is seized from the seventh level of auxiliary selector AS3 and a busy trunk condition is found, consequent to thereafter progressing the call under automatic directive control of the seized storing device (having in mind that relay 603' will actuate consequent to the seizure of 105 the storing device), the relay 105' will actuate, and if the storing device is seized from the eighth bank level and a busy trunk condition is found, consequent to thereafter progressing the call under automatic directive control of the seized storing device, there will be no alternative route 110 available. However, if the storing device is seized from the third bank level and a busy trunk condition is found, relay 701' will actuate regardless of the setting of the wiper set 411 to 414, having in mind that when the set of bank contacts 421 to 425 is concerned directive call 115 impulses are not transmitted, since the storing device is forthwith restored. The restoration of the storing device consisting of Figs. 17, 18 and 120 5 will occur when ground is removed from bank contact 334 (assuming the seizure occurred at the third level), which condition ensues consequent to the restoration of auxiliary selector AS3. 125

Calls to the various ten-thousand groups are metered as follows, having reference to Fig. 7. The numbered parts in Fig. 7 will index their respective location in other figures. Well known meter devices 702 to 707 are wired to bank contacts 710 to 715 respectively. The latter said bank contacts are cooperative with the added wiper 701 and multiplied corresponding bank contacts accessible to wipers corresponding to wiper 701 enable the meter devices to operate commonly to a plurality of storing devices for like settings. 130 Bank contact 437 is wired through the winding of slow-releasing relay 720 to wiper 411 in lieu of being directly connected thereto as in previous descriptions. At the time ground is derived over wiper 429, bank contact 437, wiper 411 relay 720 will actuate and apply said ground through make-before-break spring 721, wiper 701, its engaged bank contact to the corresponding meter device to operate it one time. Since there is a meter device for each bank position 135 of the shaft wipers, a registration will be made each time any storing device initiates its sending of directive impulses. These registrations will be specific to each routing of the call. 140

Where the alternative calling numbers are 150

used, as for example, wherein the auxiliary selector AS3 rotates-in at the "O" level and idly seizes, ground will be applied to the winding of relay 725, causing the latter said relay to actuate and apply the said ground through its make-before-break spring 927 to meter device 706 to cause it to register one time. It will be noted here that the setting of wipers 411 to 414 and 701 upon bank contacts 445 to 448 and 714 will refer to a similar call extension as the latter, so that regardless of which calling number prefix is used for a specific ten-thousand group the same meter will register. It will be manifest that the resting contact cooperative with spring 727 may extend to an individual meter device (not shown) similar to 706 to make an independent registry of the calls made by five digit series to a specific ten-thousand group. In the same manner, if the auxiliary selector AS3 rotates-in at the seventh or the eighth level, relay 728 will actuate and apply ground impulses through armature 730 or 731 (depending upon which relay 617' or 603' is actuated) to meter device 703 or 705 respectively. Due to the slow-releasing characteristic of relays 720, 725, 728 and 729, the ground maintaining them actuated will be removed before their respective armatures retract so that the meter device will not be re-energized consequent upon the retraction of the armature. The three wiper sets on shafts 703', 901' and 902' shown in Fig. 19 may each have an added wiper 701, 931' and 932' respectively, and the respective bank contact sets may have an added bank contact (not shown in Fig. 19) cooperative with the wipers like 715, for example, shown in Fig. 7, leading to a specific meter device, so that registration for each alternative routing will be specifically made. In this case, the conductor leading from the resting contact of spring 721 will lead through contacts on relays 701' and 904' to the auxiliary wipers 701, 931' and 932' correspondingly to the conductor leading from bank contact 455 in Fig. 19 with reference to wipers 414, 803' and 813'. The said bank contacts (not shown in Fig. 19) cooperative with wipers 701, 931' and 932' shown in Fig. 19 are represented by the three bank contacts 741 to 743 in Fig. 7 leading to meter devices 745 to 747 respectively, there possibly being as many of the latter said meter devices and specific bank contacts as there are bank terminal sets accessible to the wipers 701, 931' and 932', having in mind the connections shown in Fig. 7 with reference to armatures 731 and 730 on relays 603' and 617'. The meter devices 751 and 752 in Fig. 7 are operated by armatures 161' and 162' in Fig. 10. That is, when either of relays 105' or 145' operate for the objects set forth, the corresponding said meter device will register one time. The meter devices may be variably connected in the different offices or ten-thousand groups of the system to give a record of traffic over inter-office trunks and local trunks in such segregated detail as warranted, and which detail is subject to change from time to time.

Assume that Fig. 20 is substituted for Fig. 3 in the figure assembly shown in Fig. 26 wherein Fig. 20 will be joined to Fig. 9 along the dotted line *a9*. Under this modification (referred to before in paragraph "q" at the outset), the auxiliary selector AS3 is substituted by Fig. 20, which latter figure is permanently related to Fig. 9 in place of selectively related, as was auxiliary selector AS3. The element SD4 is controlled by Fig. 20 through a permanent relation with ele-

ment DS4. The armatures 908, 909, 912 and 913 will not be required, so the normal connections thereover may be made permanent. The vertical magnet VM4 and the rotary magnet RM4 are connected to bank contacts 408 and 409 respectively, in element DS4. Rotary magnet RM4 and vertical magnet VM4 are drawn in Fig. 20. The shaft operated spring sets 201'', 202'' and 203'' operate upon the shaft rotating-in at the third, seventh and eighth levels respectively. The shaft operated spring set 204'' operates upon the shaft attaining the ninth level.

It is thus clear that upon a call being initiated at telephone CT, as has been detailed, the line relay 206'' will be energized over conductors 205-302, 207''-208'' respectively. Slow-releasing relay 209'' will acutate, armature 212'' applying ground over conductor 214'' to conductor 306 to maintain the switches PL and SL in the manner described. Tone from source T20 will be applied through off-normal springs, armature 216'' to conductor 208'', audible to the calling party to index that the sending of the call may be proceeded with.

Assume that the call is destined to telephone TD, the number of which is "DAiry-3457". In the present instance the first two letters "DA" of the name will constitute the prefix, in lieu of the first three letters as before described. Upon the calling party operating the finger-hole dial in accordance with the letter "D" (corresponding to digit "3") the relay 206'' will vibrate its grounded armature 218'' three times, applying three ground impulses through sustained armature 219'', winding of slow-releasing relay 220'', conductors 221'', 336, winding of relay 403, wiper 404, bank contact 408 in element DS4 to the vertical magnet VM4 to raise the wipers 411 to 414 (shown in Figs. 9 and 20) into alignment with the third level. The relay 220'' will actuate consequent to the first one of said impulses of the series and sustain until after the last one has been sent. Consequent to the first attraction of armature 218'', following its first retraction, ground from said armature 218'' will be applied through armature 223'', off-normal springs to the winding of relay 225'', the latter relay actuating and locking through the added armature 227'' on the rotary magnet RM4 (shown in Figs. 4 and 20) to armature 228''. At the termination of the said first series of three impulses, armature 223'' will retract, whereupon ground from armature 218'' will be applied through armatures 223'' and 231'', conductor leading to bank contact 409 in element DS4 to the rotary magnet RM4 to rotate wipers 411 to 414 into engagement with the first set of bank contacts and to open the locking path of relay 225'' at armature 227''.

In this connection, it will be understood that the first set of bank contacts of the third level of element SD4 will be dead, the set of bank contacts 481 to 484 being now assumed to be the second set in and to be in the third bank level, in lieu of the first set in the second bank level, since the first two letters of the prefix name are all that has calling significance. The object of employing a dead bank position will appear presently. When the shaft rotates-in at the third level, spring set 201'' grounds conductor 235'' leading through armatures 901, 902 to the winding of relay 903, the latter said relay actuating.

At the termination of the said first series of three impulses, the armature of relay 403 in Fig. 9 will retract, permitting the wipers of element

- DS5 to advance one step so wiper 404 will rest upon bank contact 409. Then, when the second series of one impulse constituted in the letter "A" is sent by the calling party wherein armature 5 218" will retract and reactuate one time, ground will be applied therefrom over armature 219", off-normal springs, armature 236", conductors 221", 336, winding of relay 403, wiper 404, bank contact 409 to the rotary magnet RM4, effective 10 to advancing the wiper set 411 to 414 into engagement with the set of bank contacts 481 to 484 respectively. The relay 220" is thus disabled by reason of being short-circuited upon its armature 236" retracting at the termination of the 15 said first series. Ground from armature 500 in Fig. 5 applied over conductor 337, conductor 237", winding of relay 238" to upper armature of relay 209" will operatively energize the latter said relay, so the relay 212 in selector S2 will be operationally energized over conductors 217—218 and 241"—242" respectively, and armature 243". Relay 212 will thus be under control of armature 500 in the manner previously described in relation to other organizations. The sending of the 20 four local digits "3457" will cause the elements A5, B5, C5 and D5 to be set in the manner before described, the elements DS4 and ND4 functioning as when Fig. 3 cooperated with Fig. 9 in foregoing descriptions. When bank contact 478 25 in element ND4 is grounded by wiper 426, this ground is communicated over conductors 368, 245" to energize relay 230, having in mind the storing device will have sent the interpreted prefix digits "4672", followed by the local digits 30 "3457", the storing device, selector S2 and succeeding switches operating as when the said call was made, employing a three-digit prefix in lieu of the two-digit prefix. When relay 230 actuates and deenergizes relays 208" and 209", the 35 ground on armature 218" will be applied through armature 219", off-normal springs to the release magnet, the lower armatures on relays 602 and 903 not being now necessary, the off-normal springs in set ON20 concerning the release magnet Re4, being the equivalent of the off-normal spring set ON4.
- If the calling party should abandon the call by replacing his receiver after sending only part 40 of the train of directive impulse series, the relay 440 will operate in the manner before described to apply ground through armature 901; but this time over conductor 235" (spring set 201" being normal after the shaft restores), armature 212", conductors 214", 306, armature 207 to conductor 208 to guard the trunk corresponding to selector S2 against seizure until relay 440 deactuates upon all elements of the storing device restoring. 45
- In view of the foregoing, it is clear that the 50 wipers 411 to 414 can be set upon any desired set of cooperating bank contacts, having in mind that they will occupy lateral positions consistent with the first lateral position being dead due to the rotary magnet operating one time from the 55 impulse applied automatically thereto consequent to the retraction of the armature 223" at the termination of the first directive series. It will be manifest that by having a set of normally open shaft-operated contacts (not shown) in the 60 path between the make contact of armature 231" and bank contact 409 which will only close when wiper shaft carrying wipers 411 to 414 is operating with relation to the seventh, eighth, ninth and tenth levels, the bank contacts in element 65 70 75 SD4 may be connected as shown in Figs. 4 and 9
- without regard to the dead first off-normal rotary position referred to.
- If the alternative calling number is employed wherein the prefix consisting of one series of seven impulses is sent and the wipers 411 to 414 are caused to rotate-in at the seventh level, spring set 202" will operate consequent to the first rotary step imparted by the retraction of armature 223" and apply ground over conductors 247", 366 to operate relay 603' in the manner and for the purpose described. In the same manner, if the shaft is operated with respect to the eighth level, the spring set 203" will operate and apply ground over conductors 248", 376 to operate relay 617".
- If an alternative calling number (for prefix "Editor") is employed wherein the prefix consisting of one series of nine impulses is sent, spring set 204" will operate consequent to the shaft attaining the ninth level. Then, upon grounded armature 251" retracting, the ground will be applied through spring set 204", conductors 245", 342, armature 229 to the winding of relay 230 to cause it to actuate and lock to conductor 208 and also be applied through spring 225 to actuate relay 227 so the selector S2 will thereupon function on its normal level in the manner and for the object as has been described.
- If an alternative calling number (for prefix "Federal") is employed wherein the prefix consisting of one series of ten impulses is sent, spring set 204" will, as before, operate consequent to the shaft attaining the ninth level and remain operated when it attains the tenth level. When the armature 218" retracts to impart the tenth impulse to the vertical magnet VM4 ground will also be applied thereby through spring set 204", conductors 255", 358, relay 260 in selector S2 to the vertical magnet VM2 to raise the shaft of said selector S2 into alignment with the first off-normal level contacts. Then, when armature 251" retracts, relay 230 will actuate and lock. Spring 225 being disengaged, the relay 227 will not actuate until the shaft steps off-normal and closes ground through armature 235, off-normal springs to the winding of relay 227. The shaft of selector S2 will selectively operate in relation to the first off-normal level in the manner before described. The release magnet Re4 will operate consequent to the actuation of relay 230, causing the restoration of the storing device elements to normal.
- With further reference to the adaptation involving Fig. 20, it will be manifest that if the said alternative one series prefix calling numbers do not correspond to a set of bank contacts accessible to its wipers 411 to 414 reached by calling two digits, the corresponding spring set or sets 202" and 203" will not be required, and in that event corresponding associated circuits in Fig. 9 will not be required.
- Introducing Fig. 11 into Figs. 20 and 2 in the manner of applying it to Figs. 2 and 3 provides for resending the call over an alternative inter-office trunk route when calling telephones through either the "Deacon" or the "Dairy" offices if the call cannot be completed over the primary inter-office trunk route because of all trunks of a group encountered being busy. Also, by introducing cam-springs as LR in Fig. 12 into the inter-office trunk selectors and introducing Fig. 10 into Fig. 9, the operation of the system using the prefix consisting of two series in lieu of three series, will be clear. That is, by including the operating winding of relay 385 into con-

ductor 241" of Fig. 20, and introducing armature 388 and its resting contact into conductor 245" at a point in Fig. 20 to the left of the branch to the spring of set 204", and wherein conductor 387 will be connected with relation to armature 386 and the resting contact of armature 262 to the upper off-normal spring of selector S2 as shown in Fig. 11 the call will be sent over the alternative inter-office trunk route upon relay 385 actuating. This also applies when Figs. 17, 18 and 19 are employed as introduced into Fig. 9. In this latter instance two alternative trunk routes are adapted to be set-up coincident with the primary setting.

15 The present system therefore contemplates variously applying and cooperating the apparatus described depending upon traffic conditions, location of containing officers and other factors. Of course, modifications and adaptations of the 20 system contained in the invention other than have been specifically exemplified will be employed in a commercial embodiment of the system, and the modifications exemplified may be employed either as an amplification or curtailment thereof 25 without departing from the scope of the invention as defined by the claims.

I claim:—

1. In an automatic telephone system, calling and called lines, switch mechanism, trunk linking switches, a calling dial on the calling line for transmitting series of directive control impulses, a storing device, an auxiliary switch, means whereby consequent upon the initiation of a call on the calling line the said mechanism will automatically connect the calling line to the auxiliary switch whereby the said auxiliary switch may be thereafter directly directly operated from the calling dial to connect with the storing device, means whereby the calling dial may be thereafter operated in correspondence with the calling number of the called line to set-up a condition in the storing device to cause it to automatically self-operate to successively directly control the said linking switches to extend a connection to the called line and thereafter automatically join the calling and called extensions and incidentally disconnect the storing device from the connection, means dependent upon a predetermined first series of directive control impulses constituted in the first digit of the calling number of the called line sent from the dial which will directly operate a first one of the linking switches from the dial, and means whereby when the latter said switch is operated it will be into connection with a successive trunk link of the call the storing device being incidentally disconnected from the connection whereby annexing from the dial the remaining digit series of directive impulses constituted in the calling number of the called line will be effective to directly directly progress the call from the said successive trunk link through the remaining said switches to the called line.

2. In an automatic telephone system, calling and called lines, switch mechanism, trunk linking switches, a calling dial on the calling line for transmitting series of directive control impulses, a storing device, an auxiliary switch, means whereby consequent upon the initiation of a call on the calling line the said mechanism will automatically connect the calling line to the auxiliary switch whereby the said auxiliary switch may be thereafter directly directly operated from the calling dial to connect with the storing device, means whereby the calling dial may be there-

after operated in correspondence with the calling number of the calling line to set-up a condition in the storing device to cause it to automatically self-operate to successively directly control the said linking switches to extend a connection to the called line and thereafter automatically join the calling and called extensions and incidentally disconnect the storing device from the connection, means dependent upon a predetermined first series of directive control impulses constituted in the first digit of the calling number of the called line sent from the dial which will directly operate a first one of the linking switches from the dial, and means whereby when the latter said switch is operated it will be into connection with a successive trunk link of the call the storing device being incidentally disconnected from the connection whereby annexing from the dial the remaining digit series of directive impulses constituted in the calling number of the called line will be effective to directly directly progress the call from the said successive trunk link through the remaining said switches to the called line, leaving the storing device subject to use in a new call forthwith upon the said disconnection thereof and before the call is further completed.

3. In an automatic telephone system, calling and called lines, a first one of a plurality of linking switches each terminating a link for linking a connection from the calling line to the called line, a calling dial on the calling line for transmitting series of directive control impulses, a storing device, an auxiliary switch, means whereby the said auxiliary switch may be directly operated from the calling dial to connect with the storing device, means whereby the calling dial may be thereafter operated in correspondence with the calling number of the called line to set-up a condition in the storing device to cause it to automatically self-operate to directly control the said linking switches to extend a connection therefrom to the called line and thereafter automatically join the calling and called extensions and incidentally disconnect the storing device from the connection, means dependent upon a predetermined first series of directive control impulses constituted in the calling number of the called line sent from the dial which will operate the said first one of the linking switches, and means whereby when the latter said switch is operated it will be into connection with a successive link of the call and incidentally disconnect the storing device from the connection and join the calling and called extensions whereby annexing the remaining series of the calling number of the called line from the dial will be effective to directly directly progress the call from the said successive link through the remaining said switches to the called line.

4. In an automatic telephone system, calling and called lines, a first one of a plurality of linking switches each terminating a link for linking a connection from the calling line to the called line, a calling dial on the calling line for transmitting series of directive control impulses, a storing device, means whereby the calling dial may be operated in correspondence with the calling number of the called line to set-up a condition in the storing device to cause it to automatically self-operate to directly control the said linking switches to extend a connection therefrom to the called line and thereafter automatically join the calling and called extensions and incidentally disconnect the storing device

from the said successive link through the remaining said switches to the called line, leaving the storing device subject to use in a subsequent call before the call has been completed.

5 10. In an automatic telephone system, a calling line, a calling dial on the calling line for transmitting digit series of directive control impulses, a switch subject to control of a said series, and means whereby the first impulse of the series 10 for operating the switch will not affect the switch while the last impulse of the series will be effective to the switch.

11. In an automatic telephone system, calling and called lines, a first one of a plurality of linking switches each terminating a link for linking a connection from the calling line to the called line, a calling dial on the calling line for transmitting series of directive control impulses corresponding to the prefix and the local digits of the 20 called line, the prefix for causing the progress of the call through the said first switch, the local digits for causing the progress of the call through the remainder of the said switches to the called line, a storing device, an auxiliary switch for seizing the storing device over any of a plurality of paths, means for directly operating the auxiliary switch responsive to the sending of the 25 prefix digit from the dial whereby the auxiliary switch will seize the storing device over any said path at will in correspondence with the prefix digit sent, means responsive to selecting the storing device depending upon the path thereto used which will cause the storing device to correspondingly automatically directly progress the call through the said first switch in the direction of the line called to the office containing the called line, and means whereby annexing the local digits from the dial will cause the call to be further progressed to the called line.

40 12. In an automatic telephone system, calling and called lines, a first one of a plurality of linking switches each terminating a link for linking a connection from the calling line to the called line, a calling dial on the calling line for transmitting series of directive control impulses corresponding to the prefix and the local digits of the called line, the prefix for causing the progress of the call through the said first switch, the local digits for causing the progress of the call through the remainder of the said switches to the called line, a storing device, an auxiliary switch for seizing the storing device over any of a plurality of paths, means for directly operating the auxiliary switch responsive to the sending of the prefix 45 from the dial whereby the auxiliary switch will seize the storing device over any said path at will in correspondence with the prefix sent, means responsive to selecting the storing device depending upon the path thereto used which will cause the storing device to correspondingly automatically directly progress the call through the said first switch in the direction of the line called, and means whereby annexing the local digits from the dial will cause the call to be further 50 progressed to the called line.

70 13. In an automatic telephone system, calling and called lines, a first one of a plurality of linking switches each terminating a link for linking a connection from the calling line to the called line, a calling dial on the calling line for transmitting series of directive control impulses corresponding to the prefix and the local digits of the called line, the prefix for causing the progress of the call through the said first switch, the local digits for 75 causing the progress of the call through the re-

mainder of the said switches to the called line, a storing device, an auxiliary switch for seizing the storing device over any one of a plurality of paths, means for directly operating the auxiliary switch responsive to the sending of the prefix from the dial whereby the auxiliary switch will seize the storing device over any said path at will in correspondence with the prefix sent, means responsive to the selecting of the storing device depending upon the certain one of the paths thereto used which will cause the storing device to correspondingly automatically directly progress the call through the said first switch over one of the corresponding plurality of routes in the direction of the called line, means whereby selecting the storing device over another one of the said plurality of routes will not be effective to causing the storing device to be automatically directly operative to progress the call until it is directly set responsive to annexed prefix series sent from the dial whereupon it will automatically directly progress the call in the direction of the called line, and means whereby annexing the local digits from the dial will cause the call to be further progressed to the called line effective after the storing device has operatively responded to the prefix sent from the dial.

14. In an automatic telephone system, calling and called lines, a first one of a plurality of linking switches each terminating a link for linking a connection from the calling line to the called line, a calling dial on the calling line for transmitting series of directive control impulses corresponding to the prefix and the local digits of the called line, the prefix for causing the progress of the call through the said first switch, the local digits for causing the progress of the call through the remainder of the said switches to the called line, a storing device, an auxiliary switch for seizing the storing device over any one of a plurality of paths, means for directly operating the auxiliary switch responsive to the sending of the prefix from the dial whereby the auxiliary switch will seize the storing device over any said path at will in correspondence with the prefix sent, 105 means responsive to the selecting of the storing device depending upon the certain one of the paths thereto used which will cause the storing device to correspondingly automatically directly progress the call through the said first switch over one of the corresponding plurality of routes in the direction of the called line, means whereby selecting the storing device over another one of the said plurality of routes will not be effective to causing the storing device to be automatically directly operative to progress the call until it is directly set responsive to an annexed prefix series sent from the dial whereupon it will automatically directly progress the call in the direction of the called line, and means whereby annexing the local digits from the dial will cause the call to be further progressed to the called line effective after the storing device has operatively responded to the prefix sent from the dial.

15. In an automatic telephone system, calling and called lines, a first one of a plurality of linking switches each terminating a link for linking a connection from the calling line to the called line, a calling dial on the calling line for transmitting series of directive control impulses corresponding to the prefix and local digits of a called line, the prefix for causing the progress of the call over a preliminary section of the call route, the local digits for completing the call from the said preliminary section to the called line, a storing device,

- switch mechanism for seizing the storing device, means for directly operating the auxiliary switch mechanism responsive to the sending of the prefix from the dial whereby the auxiliary switch will seize the storing device over any said path at will in correspondence with the prefix sent, means responsive to selecting the storing device depending upon the path thereto used which will cause the storing device to automatically directly progress the call through the said first switch and over a corresponding one of a plurality of said preliminary sections, and means whereby annexing the local digits from the dial will cause the call to be completed to the called line.
16. In an automatic telephone system, calling and called lines, a first one of a plurality of linking switches each terminating a link for linking a connection from the calling line to the called line, a calling dial on the calling line for transmitting series of directive control impulses corresponding to the prefix and local digits of a called line, the prefix for causing the progress of the call over a preliminary section of the call route, the local digits for completing the call from the said preliminary section to the called line, a storing device, switch mechanism for seizing the storing device, means for directly operating the auxiliary switch mechanism responsive to the sending of the prefix from the dial whereby the auxiliary switch will seize the storing device over any said path at will in correspondence with the prefix sent, means responsive to selecting the storing device depending upon the path thereto used which will cause the storing device to automatically directly progress the call through the said first switch and over a corresponding one of a plurality of said preliminary sections, and means whereby annexing the local digits from the dial will cause the call to be completed to the called line under automatic directive control of the storing device.
17. In an automatic telephone system, calling and called lines, a first one of a plurality of linking switches each terminating a link for linking a connection from the calling line to the called line, a calling dial on the calling line for transmitting series of directive control impulses corresponding to the prefix and local digits of a called line, the prefix for causing the progress of the call over a preliminary section of the call route, the local digits for completing the call from the said preliminary section to the called line, a storing device, switch mechanism for seizing the storing device, means for directly operating the auxiliary switch mechanism responsive to the sending of the prefix from the dial whereby the auxiliary switch will seize the storing device over any said path at will in correspondence with the prefix sent, means responsive to selecting the storing device depending upon the specific one of the paths thereto used which will cause the storing device to correspondingly automatically directly progress the call through the said first switch over one of a corresponding plurality of preliminary sections in the direction of the line called, means whereby selecting the storing device over another one of the said plurality of sections will not be effective to causing the storing device to automatically directly progress the call until it is directly set responsive to annexed series sent from the dial whereupon it will automatically directly progress the call over a corresponding preliminary section in the direction of the called line, and means whereby annexing the local digits from the dial will cause the call to be further progressed to the called line effective after the storing device has operatively responded to the prefix sent from the dial.
18. In an automatic telephone system, calling and called lines, a calling dial on the calling line for transmitting series of directive control impulses corresponding to the prefix and local digits constituting the calling number of the called line, alternative prefixes for the called line, a storing device, means for operating the dial employing one said prefix and local digits to directly progress the call from the calling line to the called line, and means whereby the dial can be operated employing another said prefix to select the storing device and thereafter operated to set-up a condition in the storing device in accordance with the latter said prefix and local digits to cause the call to be completed to the said called line under automatic directive control of the storing device.
19. In an automatic telephone system, calling and called lines, a calling dial on the calling line for transmitting series of directive control impulses corresponding to the prefix and local digits constituting the calling number of the called line, alternative prefixes for the called line, a storing device, means for operating the dial employing one said prefix and local digits to directly progress the call from the calling line to the called line, and means including the storing device whereby the dial can be operated employing another said prefix involving a different number of series than involved in the first said prefix to cause the call to be completed to the called line.
20. In an automatic telephone system, calling and called lines, a calling dial on the calling line for transmitting series of directive control impulses corresponding to the prefix and local digits constituting the calling number of the called line, alternative prefixes for the called line, a storing device, means for operating the dial employing one said prefix and local digits to directly progress the call from the calling line to the called line, and means including the storing device whereby the dial can be operated employing another said prefix involving a different number of series than involved in the first said prefix, the storing device responding to the dial and thereafter re-sending series effective to progress the call from the calling to the called line.
21. In an automatic telephone system, calling and called lines, a calling dial on the calling line for transmitting series of directive control impulses corresponding to the prefix and local digits constituting the calling number of the called line, alternative prefixes for the called line, a storing device, means for operating the dial employing one said prefix and local digits to directly progress the call from the calling line to the called line, and means including the storing device whereby the dial can be operated employing another said prefix involving a different number of series than involved in the first said prefix, the storing device responding to the dial and thereafter re-sending series effective to progress the call from the calling to the called line regardless of which prefix is sent from the dial.
22. In an automatic telephone system, calling and called lines, a calling dial on the calling line for transmitting series of directive control impulses corresponding to the prefix and local digits constituting the calling number of a called line, the prefix corresponding to a preliminary

- section of the called line connection and the local digits corresponding to the completing section of the connection, a storing device interposed to receive the directive control impulse 5 series from the dial and then automatically send interpreted directive control impulses therefrom in series to correspondingly progress the call to the called line, and means whereby an alternative prefix constituting a different number of 10 series as sent from the dial will cause the storing device to effectuate the same interpreted directive control impulse series to progress the call over the preliminary section of the connection in the direction of the said called line.
- 15 23. In an automatic telephone system, calling and called lines, a calling dial on the calling line for transmitting series of directive control impulses corresponding to the prefix and local digits constituting the calling number of a called 20 line, the prefix corresponding to a preliminary section of the called line connection and the local digits corresponding to the completing section of the connection, a storing device interposed to receive the directive control impulse series from the dial and then automatically send interpreted directive control impulses therefrom in series to correspondingly progress the call to the called line, and a meter device which will record the number of calls progressed over the 25 preliminary section.
- 30 24. In an automatic telephone system, calling and called lines, a calling dial on the calling line for transmitting series of directive control impulses corresponding to the prefix and local digits constituting the calling number of a called line, the prefix corresponding to a preliminary section of the called line connection and the local digits corresponding to the completing section of the connection, a storing device interposed to receive the directive control impulse series from the dial and then automatically send interpreted directive control impulses therefrom in series to correspondingly progress the call to the called line, and means whereby an alternative 40 prefix constituting a different number of series as sent from the dial will cause the storing device to effectuate the same interpreted directive control impulse series to progress the call over the preliminary section of the connection in the direction of the said called line, and a meter device which will record the number of calls progressed with reference to the said preliminary section, regardless of which alternative prefix is used.
- 45 25. In an automatic telephone system, calling and called lines, a calling dial on the calling line for transmitting series of directive control impulses corresponding to the prefix and local digits constituting the calling number of a called line, the prefix corresponding to a preliminary section of the called line connection and the local digits corresponding to the completing section of the connection, a storing device interposed to receive the directive control impulse series from the dial and then automatically send interpreted directive control impulses therefrom in series to correspondingly progress the call to the called line, and means whereby an alternative prefix constituting a different number of series as sent from the dial will cause the storing device to effectuate the same interpreted directive control impulse series to progress the call over the preliminary section of the connection in the direction of the said called line, and a meter 50 mechanism which will record the number of calls progressed with reference to the said preliminary section, regardless of which alternative prefix is used.
- 55 26. In an automatic telephone system, a directly controlled connective switch, a calling line, 80 a directive calling dial on the calling line for sending directive impulse series constituting digits, a trunk line accessible from the said switch, and means whereby only a portion of the last impulses of a single digit series sent from the dial will be effective to directly operate the switch to extend the connection to the trunk line.
- 60 27. In an automatic telephone system, a directly controlled connective switch, a calling line, 85 a directive calling dial on the calling line for sending directive impulse series constituting digits, a trunk line accessible from the said switch, and means whereby the first impulse of a single digit series of directive impulses will not be effective to the switch, but that following impulses of the said series will be effective to the switch.
- 65 28. In an automatic telephone system, a directly controlled connective switch, a calling line, 90 a directive calling dial on the calling line for sending directive impulse series constituting digits, a trunk line accessible from the said switch, and means whereby the first impulse of a single digit series of directive impulses will not be effective to the switch but that the switch will operate consistent with the said series sent.
- 70 29. In an automatic telephone system, a directly controlled connective switch, a calling line, 95 a directive calling dial on the calling line for sending directive impulse series constituting digits, a trunk line accessible from the said switch, and means whereby only the last impulse of a single digit series will be effective to the switch to link the calling line to the trunk line.
- 75 30. In an automatic telephone system, calling 100 and called lines, linking switches terminating trunk links, a calling dial on the calling line for transmitting series of directive impulses for causing the operation of certain ones of the said switches to progress a connection from the calling line in the direction of the called line, means effective consequent upon a said trunk link being encountered as busy the progressed portion of the call will be automatically effaced and a re-progression of the call will then be automatically made involving a link other than the said busy link whereby the call will be again progressed in the direction of the called line, and means whereby consequent to a said trunk link being encountered as busy when making the said 110 re-progression of the call the call will be again effaced and automatically re-progressed involving links other than the said busy links so that the call will be again re-progressed automatically from the calling line in the direction of the called line, the said re-progressions being without specific dial control.
- 80 31. In an automatic telephone system, calling and called lines, linking switches terminating 115 trunk links, a calling dial on the calling line for transmitting series of directive impulses for causing the operation of certain ones of the said switches to progress a connection from the calling line in the direction of the called line, and means effective consequent upon a said trunk link being encountered as busy the progressed portion of the call will be automatically effaced and a re-progression of the call will be then automatically made involving a link other than the said busy link whereby the call will be again pro-

gressed in the direction of the called line the re-progression being made without specific dial control, and means for recording the number of times calls are re-progressed.

- 5 32. In an automatic telephone system, calling and called lines, linking switches terminating trunk links, a calling dial on the calling line for transmitting series of directive impulses for causing the operation of certain ones of the said switches to progress a connection from the calling line in the direction of the called line, means effective consequent upon a said trunk link being encountered as busy the progressed portion of the call will be automatically effaced and a re-progression of the call will then be automatically made involving a link other than the said busy link whereby the call will be again progressed in the direction of the called line, means whereby consequent to a said trunk link being encountered as busy when making the said re-progression of the call the call will be again effaced and automatically re-progressed involving links other than the said busy links so that the call will be again re-progressed automatically from the calling line in the direction of the called line, the said re-progression being without specific dial control, and means for recording the number of times calls are again re-progressed.
33. In an automatic telephone system, calling and called lines, linking switches terminating trunk links, a calling dial on the calling line for transmitting series of directive impulses for causing the operation of certain ones of the said switches to complete a connection from a calling line to an office containing a called line, means whereby if a busy trunk link condition is found when progressing a call the progressed extension of the call will be automatically effaced and a re-progression of the call will be automatically made, and means whereby if a busy trunk link condition is again found the progressed extension of the call will be again automatically effaced and another re-progression of the call will be automatically made, the re-progressions of the call being without specific directive control from the dial and involving links other than these encountered as busy whereby the call will be progressed to the said office and then completed to the said called line without the party operating the dial being aware of the said busy conditions encountered.

34. In an automatic telephone system, calling and called lines, a plurality of trunk routes between a said calling and called line, a dial on the calling line for directly extending a call over a first one of said trunk routes to the called line, automatic means whereby if the call cannot be completed over said first route due to a busy trunk condition the call extension will be automatically effaced and then automatically re-extended over a second of said routes in the direction of the called line, and automatic means whereby if the call cannot be completed over said second route due to a busy trunk condition the said re-extension of the call will be automatically effaced and then again re-extended over a third one of said routes in the direction of the called line.

35. In an automatic telephone system, calling and called lines, a plurality of trunk routes between a said calling and called line, an attendant's station, a dial on the calling line for directly extending a call over a first one of said trunk routes to the called line, automatic means whereby if the call cannot be completed over said first route due to a busy trunk condition the call exten-

sion will be automatically effaced and then automatically re-extended over a second of said routes in the direction of the called line, and automatic means whereby if the call cannot be completed over said second route due to a busy trunk condition the call re-extension will be automatically effaced and then automatically again re-extended to the attendant's station.

36. In an automatic telephone system, calling and called lines, a calling dial on the calling line, a storing device, means for setting-up a condition in the storing device responsive to effecting the calling line number from the dial wherein the storing device will involve a stored condition for re-sending directive impulse series for progressing the call from the calling line to the called line over a first and also an alternative route, and automatic means effective upon a busy condition being encountered while the call is being progressed by the storing device to efface the call progression and then automatically re-progress the call over the said alternative route without specific dial operation.

37. In an automatic telephone system, calling and called lines, a calling dial on the calling line, a storing device, means for setting-up a condition in the storing device responsive to effecting the calling line number from the dial wherein the storing device will involve a stored condition for re-sending directive impulse series for progressing the call from the calling line to the called line over a first and also a first and a second alternative route, automatic means effective upon a busy condition being encountered while the call is being primarily progressed by the storing device to efface the call progression and then automatically re-progress the call over the said first alternative route, and means effective upon a busy condition being encountered while the call is being re-progressed by the storing device to efface the call progression and then again automatically progress the call over the said second alternative route without specific dial control therefor.

38. In an automatic telephone system, calling and called lines, a calling dial on the calling line for directly extending a call from the calling line in the direction of the called line, means whereby the dial will coincidentally potentially progress the call over a plurality of routes from the calling line to the called line, the said routes each made up of a plurality of trunk links, and means whereby the call will be successively progressed over portions of the routes respectively in predetermined order if a route having a busy said link is encountered, and means whereby the call will be progressed entirely over the first route encountered wherein all links are idle.

39. In an automatic telephone system, calling and called lines, a calling dial on the calling line for directly extending a call from its line to a called line, a plurality of trunk routes extending between the calling and the called line, each route having a numerical order of preference with relation to other said routes, each route made up of one or more trunk links, and means for initiating and for thereafter effacing the extension of the call over the routes successively, the said effacings and the initiations subsequent thereto being automatic and in the order of their preference dependent upon the busy condition of one of the links comprising the route then concerned, so that the call will be completed over the idle route having the lower order of preference with relation to other idle ones of said routes.

40. In an automatic telephone system, calling

and called lines, a calling dial on the calling lines respectively for directively extending a call from its line to a respective called line, a plurality of trunk routes extending between each calling line and its respective called line, each trunk route having a numerical order of preference with relation to other said routes from a calling line to its called line, each route made up of one or more trunk links, and means operative for initiating 5 and for thereafter effacing the extension of the call over the routes successively, the said effacing and the initiations subsequent thereto being automatic and in the order of their preference dependent upon the busy condition of one of the links 10 comprising the route then concerned, a link of a said trunk route being common to a plurality of trunk routes concerned in calls between different calling and called lines and not having the same order of preference with reference to the respective 15 said calling and called lines.

41. In an automatic telephone system, calling and called lines, a calling dial on the calling line for transmitting directive control series, each series constituting a directive control digit of the calling number of the called line, an interposed 20 storing device for receiving the respective series sent from the dial and then itself sending spaced series automatically with predetermined correspondence to the series sent from the dial effective to a plurality of linking switches successively 25 to link a connection from a calling to a called line, and means for shortening the normal spacing between two series sent from the storing device after the operation of the first affected switch 30 regardless of the normal spacing of the series as sent from the dial.

42. In an automatic telephone system, subscribers' lines grouped so that the lines of different groups terminate in different offices, between 40 which trunk connections may be established, and in which said trunk connections may be established through switching machinery under the control of dials, the method which consists in applying letters to the dial so that at least one 45 letter is correlated with each of a group of numerals on the dial, and adopting a word name for each office, said word name being made up of letters, a combination of which letters and numerals is dialed for controlling connections for that office, and an office name correlated with a numeral on 50 the dial which name may be dialed in combination with the plurality of numerals in the same combination as before to alternatively control a connection involving the same trunk route and called telephone as when the plurality of said letters and numerals is dialed in lieu of the corresponding named numeral.

43. In an automatic telephone system, subscribers' lines grouped so that the lines of different groups terminate in different offices, between 60 which trunk connections may be established, and in which said trunk connections may be established through switching machinery under the control of dials, the method which consists in applying letters to the dial so that at least one letter is correlated with each of a group of numerals on the dial, and adopting a word name for each office, said word name being made up of letters, a combination of which letters and numerals is dialed for controlling connections for that office, and an office name correlated with a numeral on 65 the dial which name may be dialed in combination with the plurality of numerals in the same combination as before to alternatively control a connection involving the same called tele-

phone as when the plurality of said letters and numerals is dialed in lieu of the corresponding named numeral.

44. In an automatic telephone system, subscribers' lines grouped so that the lines of different groups terminate in different offices, between which trunk connections may be established, and in which said trunk connections may be established through switching machinery under the control of dials, the method which consists in applying letters to the dial so that at least one letter is correlated with each of a group of numerals on the dial, and adopting a word name for each office, said word name being made up of letters, a combination of which letters and numerals is dialed for controlling connections for that office, and an office name correlated with one or more numerals respectively on the dial which name may be dialed in combination with the plurality of numerals in the same combination as before to alternatively control a connection involving the same trunk route and called telephone as when the plurality of said letters and numerals is dialed in lieu of the corresponding named numeral. 80

45. In a telephone exchange system, calling lines, called lines, selective switches for extending a calling line to one of said called lines, a mechanism accessible in common to a plurality of selective switches for controlling the operation thereof, means in said mechanism for recording the designation of a called line, means operable in accordance with said recorded designation for causing said selective switches to operate to extend the calling line, means for nullifying a portion of said recorded designation and for causing one of said switches to extend said calling line towards said called line independently of the designation of said called line, and means for completing the extension of said calling line to 100 said called line in accordance with said recorded designation. 105

46. In a telephone exchange system, a calling line, a called line, a first office in which said calling line terminates, a second office in which 110

said called line terminates, a plurality of connecting trunks between said first and second offices, a plurality of selective switches for extending said calling line to said called line, a mechanism accessible in common to a plurality of selective switches for controlling the operation thereof, means in said mechanism for recording the designation of a called line, means operable in accordance with the said recorded designation for causing said selective switches to operate to extend the calling line, means dependent upon the condition of said plurality of trunks for nullifying a portion of said recorded designation and for causing one of said switches to extend said calling line towards said called line independently of the designation of said called line, and means for completing the extension of said calling line to 120 said called line in accordance with said recorded designation. 125

47. In a telephone exchange system, a calling line, a called line, a first office in which said calling line terminates, a second office in which 130

said called line terminates, a plurality of connecting trunks between said first and second offices, a

plurality of selective switches for extending said calling line to said called line, a mechanism accessible in common to a plurality of selective switches for controlling the operation thereof, means in said mechanism for recording a portion of the designation of the called line, means 140

for causing one of said switches to extend said calling line towards said called line independently of the designation of said called line, and means for completing the extension of said calling line to said called line in accordance with said recorded designation. 145

48. In a telephone exchange system, a calling line, a called line, a first office in which said calling line terminates, a second office in which 150

said called line terminates, a plurality of connecting trunks between said first and second offices, a

- in said mechanism for testing the condition of said plurality of trunks, means dependent upon the condition of said testing means for rendering said recorded designation ineffective and for 5 causing one of said switches to extend said calling line towards said called line independently of the designation of said called line, and means for completing the extension of said calling line to said called line in accordance with said recorded designation. 10
48. In a telephone exchange system, a calling line, a called line, a first office in which said calling line appears, a second office in which said called line appears, a plurality of selective switches for extending said calling to said called line, a first set of trunks for interconnecting certain of the selective switches of the first office, a second set of trunks for interconnecting the selective switches of the first and second offices, a 15 mechanism in said first office accessible in common to a plurality of calling lines for controlling the operation of the selective switches in said first office, means in said mechanism for recording the designation of said called line and for testing 20 the condition of said plurality of sets of trunks, means operable in accordance with said recorded designation for directly operating a plurality of selective switches in said first office, means dependent upon the condition of said second set 25 of trunks for revising said recorded designation to thereby cause one of said switches to extend said calling line towards said called line, independently of the designation of said called line, and means for completing the extension of said 30 calling line to said called line in accordance with said recorded designation. 35
49. In a telephone exchange system, a calling line, a called line, a first office in which said calling line terminates, a second office in which said 40 called line terminates, a plurality of connecting trunks between said first and second offices, a plurality of selective switches for extending said calling line, a register sender for recording the complete designation of said called line, a mechanism accessible in common to a plurality of selective switches for controlling the operation thereof, means in said mechanism for translating a portion of said recorded designation, means 45 in said mechanism for testing the busy or idle condition of said plurality of trunks, means under control of the translated record for causing a plurality of selective switches to operate to extend the calling line, means under control of said testing means for nullifying said translated record and for automatically setting up a new translation to thereby cause one of said switches to partially extend the calling line independently of the designation of said called line, and means 50 for completing the extension of said calling line 55 in accordance with said complete designation. 60
50. In a telephone exchange system, a calling line, a called line, a first office in which said calling line appears, a second office in which said called line appears, a plurality of selective switches for extending said calling line to said called line, a first set of trunks for interconnecting certain of the selective switches of the first office, a second set of trunks for interconnecting the selective switches of the first and second 65 offices, a register sender for recording the complete designation of said called line, a mechanism accessible in common to a plurality of selective switches for controlling the operation thereof, means in said mechanism for receiving and translating a portion of said recorded designation. 70
- tion and for testing the condition of said second set of trunks, means under control of the translated record for directly operating a plurality of selective switches in said first office, means dependent upon the condition of said second set of trunks for rendering ineffective said translated record and for causing one of said switches to extend the calling line towards the called line independently of the designation of said called line, and means for completing the extension of said calling line to said called line in accordance with said complete designation. 75
51. In a telephone exchange system, a calling office, a called office, an intermediate office, a plurality of direct talking paths between said calling and said called office, a plurality of indirect talking paths leading from said calling office through said intermediate office to said called office, means at said calling office for making a record of the designation of said called office, means controlled by said record for directly seizing an idle one of said direct talking paths, and means effective when all the direct talking paths are busy for automatically changing said record to cause the seizure of one of said indirect talking paths. 80
52. In a telephone exchange system, a calling office, a called office, an intermediate office, a plurality of direct talking paths between said calling and said called offices, a plurality of indirect talking paths leading from said calling office through said intermediate office to said called office, recording means at said calling office, means under control of a calling subscriber for making a record on said means of the designation of said called office to directly seize an idle one of said direct talking paths, and means effective when all the direct talking paths are busy for automatically changing said record to cause the seizure of one of said indirect talking paths. 85
53. In a telephone exchange system, a calling office, a called office, an intermediate office, a plurality of direct talking paths between said calling and said called office, a plurality of indirect talking paths leading from said calling office through said intermediate office to said called office, registering and controlling senders at the said calling office, a plurality of selective switches at each of said offices, a switch controlling device at said calling office accessible in common to said senders, means for transferring a record of the designation of said called office from a selected sender to said controlling device to cause the seizure of one of said direct paths, and means effective when all said direct paths are busy for automatically changing the transferred record to cause said device to control the seizure of one of said indirect talking paths. 90
54. In a telephone exchange system, a calling office, a called office, an intermediate office, a first selective switch located in the calling office, a plurality of direct talking paths leading from said first selective switch to said called office, a plurality of indirect talking paths leading from said first selective switch through said intermediate office to said called office, means for directly seizing an idle one of said direct talking paths, and means effective when all said direct talking paths are busy at said first selective switch for automatically seizing one of said indirect talking paths at said first selective switch. 95
55. In a telephone system, a subscriber's calling line, a called line, automatic switch mechanism, connecting links, a calling device on the calling 100

line, means for initiating a call on the calling line; means responsive to the operation of the calling device after the initiation of the call for operating the switch mechanism to extend a connection from the calling line over certain of said connecting links to the called line, means responsive to abandoning the initiated call for effacing the call extension, means responsive to a barred condition being encountered in the extension of the call thereby preventing the completion of said call extension to the called line for effacing the call extension, and means for causing the effacement solely responsive to said barred condition being encountered regardless of how soon after encountering said barred condition the call is abandoned.

56. In a telephone system, a subscriber's calling line, a called line, automatic switch mechanism, connecting links, a calling device on the calling line, means for initiating a call on the calling line, means responsive to the operation of the calling device after the initiation of the call for operating the switch mechanism to extend a connection from the calling line over certain of said connecting links to the called line, means responsive to abandoning the initiated call for effacing the call extension, means responsive to a barred condition being encountered in the extension of the call thereby preventing the completion of said call extension to the called line for effacing the call extension, and means for causing the effacement of the call solely responsive to said barred condition being encountered regardless of any condition occurring on the calling line while the call is maintained non-abandoned.

57. In a telephone system, a calling line, a called line, a plurality of trunk routes between said calling and called lines, automatic switch mechanism, a manually operated calling device on the calling line for directing the operation of the switch mechanism over the calling line for extending a call extension from the calling line over one of said routes to the called line responsive to operating the calling device in correspondence with the designation of the called line, means responsive to encountering a barred trunk condition in a said trunk route thereby preventing the completion of said call extension to the called line whereby said extension will be thereby effaced and a new call extension made from the calling line over another of said trunk routes to the called line, and means responsive to operating the calling device in correspondence with the designation of the called line for effecting the connection from the calling line to the called line whether or not said effacement and new extension of the call is made.

58. In a telephone system, a calling line, a called line, a plurality of trunk routes between said calling and called lines, automatic switch mechanism, a manually operated calling device on the calling line for directing the operation of the switch mechanism over the calling line for extending a call extension from the calling line over one of said routes to the called line responsive to operating the calling device in correspondence with the designation of the called line, means responsive to encountering a barred trunk condition in a said trunk route thereby preventing the completion of said call extension to the called line whereby said extension will be thereby effaced and a new call extension made from the calling line over another of said trunk routes to the called line, and means responsive to operating

the calling device in correspondence with the designation of the called line a single time for effecting the connection from the calling line to the called line whether or not said effacement and new extension of the call is made. 80

59. In a telephone system, a calling line, a called line, a plurality of trunk routes between said calling and called lines, automatic switch mechanism, a manually operated calling device on the calling line for directing the operation of the switch mechanism over the calling line for extending a call extension from the calling line over one of said routes to the called line responsive to operating the calling device in correspondence with the designation of the called line, means responsive to encountering a barred trunk condition in a said trunk route thereby preventing the completion of said call extension to the called line whereby said extension will be thereby effaced and a new call extension made from the calling line over another of said trunk routes to the called line, and means wherein the party operating the calling device will not be aware that an effacement of the call extension has been made in effecting the connection to the called line. 90 95

60. In a telephone system, a calling line, a called line, a plurality of trunk routes between the calling and called lines, automatic switch mechanism, a manually operated calling device on the calling line for directing the operation of the switch mechanism over the calling line for extending a call extension from the calling line over one of said routes to the called line responsive to operating the calling device with correspondence to the nominal designation of the 105 called line, a storing device for receiving direction from the calling device in accordance with the nominal designation of the called line and for translating said designation to respective actual designations of the called line as determined by 110 the details of the respective said trunk routes between the calling line and the called line for directing the operation of the switch mechanism in accordance with the respective said translated designations, and means responsive to the 115 extension toward the called line becoming futile over a said trunk route due to a barred condition in said route for making a re-translation in the storing device of said nominal designation to an actual designation of the called line as determined by details of another of said trunk routes 120 wherein the call will thereupon be re-extended under direction of the storing device by the switch mechanism to the called line in accordance with the last said actual designation 125 130

61. In a telephone system, a calling line, a called line, a plurality of trunk routes between the calling and called lines, automatic switch mechanism, a manually operated calling device 135 on the calling line for directing the operation of the switch mechanism over the calling line for extending a call extension from the calling line over one of said routes to the called line responsive to operating the calling device with 140 correspondence to the nominal designation of the called line, a storing device for receiving direction from the calling device in accordance with the nominal designation of the called line and for translating said designation to respective actual 145 designations of the called line as determined by the details of the respective said trunk routes between the calling line and the called line for directing the operation of the switch mechanism in accordance with the respective said translated 150

- designations, means responsive to the extension toward the called line becoming futile over a said trunk route due to a barred condition in said route for making a re-translation in the storing device of said nominal designation to an actual designation of the called line as determined by details of another of said trunk routes wherein the call will thereupon be re-extended under direction of the storing device by the switch mechanism to the called line in accordance with the last said actual designation thereof, and means for causing a further re-translation of the nominal designation different from the antecedent ones and for causing a corresponding re-extension responsive to encountering a barred condition.
62. In a telephone system, a calling line, a called line, automatic switch mechanism, a calling device on the calling line, a storing device, means for operating the storing device over the calling line responsive to the calling device for setting up a stored condition in the storing device, means for then operating the switch mechanism in one way to effect a connection from the calling line to the called line responsive to sending a train of impulses from the said storing device, and automatic means operated independent of directive control over the calling line for causing the said stored storing device to operate the switch mechanism in an alternative way by sending a train of impulses different from first said train to effect connection from the calling line to the called line.
63. In a telephone system, a calling line, a called line, automatic switch mechanism, a calling device on the calling line, a storing device, means for operating the storing device over the calling line responsive to the calling device for setting up a stored condition in the storing device, means for then operating the switch mechanism in one way to effect a connection from the calling line to the called line responsive to sending a train of impulses from the said storing device, and automatic means operated independent of manual control specific therefor for causing the said stored storing device to operate the switch mechanism in an alternative way by sending a train of impulses different from first said train to effect connection from the calling line to the called line.
64. In a telephone system, a calling line, a called line, automatic switch mechanism, a calling device on the calling line, a storing device, means for operating the storing device over the calling line responsive to the calling device for setting up a stored condition in the storing device, means for then operating the switch mechanism in one way to effect a connection from the calling line to the called line responsive to sending a train of impulses from the said storing device, and automatic means operated independent of manual control specific therefor for causing the said stored storing device to operate the switch mechanism in any one of a plurality of predetermined different ways by sending a corresponding train of impulses different from first said train to effect connection from the calling line to the called line.
65. In a telephone system, a calling line, a called line, automatic switch mechanism, a calling device on the calling line, a storing device, means for operating the storing device over the calling line responsive to the calling device for setting up a stored condition in the storing device, means for then operating the switch mechanism in one way to effect a connection from the calling line to the called line responsive to control by the said stored storing device, and automatic means operated independent of directive control over the calling line for causing the said stored storing device to control the switch mechanism in a predetermined alternative way to effect connection from the calling line to the called line.
66. In a telephone system, a calling line, a called line, automatic switch mechanism, a calling device on the calling line, a storing device, means for operating the storing device over the calling line responsive to the calling device for setting up a stored condition in the storing device, means for then operating the switch mechanism in one way to effect a connection from the calling line to the called line responsive to control by the said stored storing device, and automatic means operated independent of directive control over the calling line for causing the said stored storing device to control the switch mechanism in any one of a plurality of predetermined different ways but determined by the condition stored in the storing device responsive to the calling device for the specific call to extend the connection from the calling line to the called line.
67. In a telephone system, a calling line, a called line, automatic switch mechanism, a calling device on the calling line, a storing device, means for operating the storing device over the calling line responsive to the calling device for setting up a stored condition in the storing device, means for then operating the switch mechanism in one way to effect a connection from the calling line to the called line responsive to control by the said stored storing device, and automatic means operated over the call extension effected by control from the stored storing device for causing the said stored storing device to control the switch mechanism in an alternative way predetermined by the stored condition of the storing device to effect connection from the calling line to the called line.
68. In a telephone system, a calling line, a called line, automatic switch mechanism, a calling device on the calling line, a storing device, means for operating the storing device over the calling line responsive to the calling device for setting up a stored condition in the storing device, means for then operating the switch mechanism in one way to effect a connection from the calling line to the called line responsive to control by the said stored storing device, and automatic means operated over the call extension effected by control from the stored storing device for causing the said stored storing device to control the switch mechanism in any one of a plurality of predetermined different ways but determined by the condition stored in the storing device responsive to the calling device for the specific call to extend the connection from the calling line to the called line.
69. In an automatic telephone system, a calling line, a calling device on the calling line, a plurality of trunk routes each consisting of a different number of trunk links, means for operating the calling device in a specific manner common to all said routes, means for causing a connection to be linked from the calling line to the called line responsive to said operation of the calling device, means for using said trunk routes in predetermined order of preference, and means dependent upon the busy condition of a said route

for causing the trunk route having the next following order of preference to be used.

70. In an automatic telephone system, a calling line, a manually operated calling device on the calling line, a plurality of trunk routes each consisting of a different number of trunk links, means for operating the calling device in a specific manner common to all said routes, means for using said trunk routes in a predetermined order of preference, means dependent upon the busy condition of a said route for causing the trunk route having the next following order of preference to be used, means for causing a connection to be linked from the calling line to the called line responsive to said operation of the calling device so that the party operating the calling device will not be aware to which said order of preference the trunk route employed in the completed connection belongs.

71. In an automatic telephone system, a calling line, called lines, a manual calling device on the calling line, automatic switch mechanism, trunk links, means responsive to operating the calling device in accordance with the designation of a random one of said called lines for directly operating the switch mechanism over the calling line to link a trunk extension from the calling line to said random called line, and means responsive to encountering a barred trunk condition preventing the completion of said extension to the random called line for effacing the extension and link a new trunk extension to said random called line without specific operation of the calling device for said new extension.

72. In an automatic telephone system, a calling line, called lines, a manual calling device on the calling line, automatic switch mechanism, trunk lines, means responsive to operating the calling device in accordance with the designation of a random one of said called lines for directly operating the switch mechanism over the calling line to link a trunk extension from the calling line to said random called line, and means responsive to encountering a barred trunk condition preventing the completion of said extension to the random called line for effacing the extension and link a new trunk extension to said random called line without specific operation of the calling device for said new extension without the party operating the calling device being aware of said effacement.

73. In an automatic telephone system, a calling line, called lines, a manual calling device on the calling line, automatic switch mechanism, a storing device, trunk links, means responsive to operating the calling device in accordance with the designation of a random one of said called lines for setting up a stored condition in the storing device directed over the calling line and specific to the said random called line, means responsive to the said stored condition for operating the switch mechanism for linking a trunk extension from the calling line to the random called line, and means responsive to encountering a barred trunk condition preventing the completion of said extension to the random called line for effacing said trunk extension and making a new trunk extension from the calling line to the random called line under directive control of the storing device without specific operation of the calling device because of said effacement.

74. In an automatic telephone system, a calling line, called lines, a manual calling device on the calling line, automatic switch mechanism, a

storing device, trunk links, means responsive to operating the calling device in accordance with the designation of a random one of said called lines for setting up a stored condition in the storing device directed over the calling line and specific to the said random called line, means responsive to the said stored condition for operating the switch mechanism for linking a trunk extension from the calling line to the random called line, and means responsive to encountering a barred trunk condition preventing the completion of said extension to the random called line for effacing said trunk extension and making a new trunk extension from the calling line to the random called line under directive control of the storing device without specific operation of the calling device because of said effacement without the party operating the calling device being aware of said effacement.

75. In a telephone system, a calling line, a called line, automatic switch mechanism, a calling device on the calling line, a storing device, means for operating the storing device over the calling line responsive to the calling device for simultaneously setting up a plurality of stored conditions in the storing device, means for then operating the switch mechanism in one way to effect a connection from the calling line towards the called line responsive to control by the said stored storing device, and automatic means operated over the call extension effected by control from the stored storing device for causing the said stored storing device to control the switch mechanism by another one of said plurality of stored conditions to effect a new connection from the calling line towards the called line.

76. In a telephone system, a calling line, a called line, automatic switch mechanism, a calling device on the calling line, a storing device, means for operating the storing device over the calling line responsive to the calling device for simultaneously setting up a plurality of stored conditions in the storing device, means for then operating the switch mechanism in one way to effect a connection from the calling line towards the called line responsive to control by the said stored storing device, and automatic means for causing the said stored storing device to control the switch mechanism by another one of said plurality of stored conditions to effect a new connection from the calling line towards the called line.

77. In an automatic telephone system, a calling line, a called line, a calling device on the calling line, a storing device, automatic switch mechanism for extending connection from the calling line to the called line, a plurality of sets of wipers of the storing device, the respective sets of wipers for setting up a different specific stored condition in the storing device, means responsive to the calling device operated over the calling line for simultaneously setting the sets of wipers, means responsive to one of said set up conditions for causing operation of the switch mechanism for extending a call from the calling line towards the called line, and automatic means for determining which said set up condition shall be effective in a connection extended by said mechanism from the calling line to the called line.

78. In an automatic telephone system, a calling line, a called line, a calling device on the calling line, a storing device, automatic switch mechanism for extending connection from the calling line to the called line, a plurality of sets of wipers of the storing device, the respective

- sets of wipers for setting up a different specific stored condition in the storing device, means responsive to the calling device operated over the calling line for simultaneously setting the sets 5 of wipers, means responsive to one of said set up conditions for causing operation of the switch mechanism for extending a call from the calling line towards the called line, and automatic means responsive to control over the said call extension 10 and exclusive of specific directive control over the calling line for determining which said set up condition shall be effective in a connection extended from the calling line to the called line.
- 15 79. In an automatic telephone system, a calling line, a called line, a calling device on the calling line, a storing device, automatic switch mechanism for extending connection from the calling line to the called line, means for operating the storing device by the calling device over the calling line to effect a stored condition in the storing device representing a defined path to the called line, means responsive to said set up condition for directively operating the switch mechanism to extend a connection from the calling line 20 over said defined path to the called line means responsive to a barred condition in said defined path being encountered to prevent the call being completed to the called line for effacing the call extension and altering only a portion of said 25 stored condition, and means responsive to said altered stored condition for directing the extension of a new call from the calling line to the called line wherein the defined path to the called line will be different than when the first call 30 extension was started.
- 35 80. In an automatic telephone system, a calling line, a called line, a calling device on the calling line, a storing device, automatic switch mechanism for extending connection from the calling line to the called line, means for setting the storing device by the calling device over the calling line to effect a stored condition in the storing device representing a defined path to the called line, means responsive to said set up condition for directively operating the switch mechanism to extend a connection from the calling line 40 over said defined path to the called line, means responsive to a barred condition in said defined path being encountered to prevent the call being completed to the called line for effacing the call extension and altering only a portion of said 45 stored condition, and means responsive to said altered stored condition for directing the extension of a new call from the calling line to the called line wherein the portion of said defined path involving said barred condition will be 50 bypassed.
- 55 81. In an automatic telephone system, a calling line, called lines, a calling device on the calling line for directing the linking of a connection from the calling line to a random said called line, and means responsive to a barred link being encountered in the said connection to render futile 60 said connection to efface the connection linked and for bypassing the barred link in a new linking to said random called line wherein specific directive operation of the calling device is not made because of the effaced connection so that the party operating the calling device will not be required to vary said operation because of said 65 new linking.
- 70 82. In a telephone system, a trunk line divided into two sections, an automatic switch connected with the second section, means operated 75
- during the course of a call for seizing the first section of said trunk line, means responsive to said seizure for connecting a register to the first section and for connecting a sender to the second section, means controlled over the calling line for setting said register switch in either of two positions, means responsive to the setting of said register switches in one position for controlling the sender to transmit impulses over the second section of said trunk line to operate the automatic switch in which said section terminates, and means immediately responsive to the setting of said register switch into the other of said positions for joining the two sections of said trunk line together and for disconnecting said register and said sender therefrom. 80
- 85 83. In a telephone system, a trunk circuit, a director and means for connecting the same to said trunk circuit, means for disconnecting the director from said trunk circuit, an office register in said director, and shaft springs on said office register for controlling said disconnecting means.
- 90 84. In a director, an office register, a director cut-off control conductor, and shaft springs on said register for grounding said conductor. 95
- 95 85. In a telephone system, a first office, a second office, a plurality of groups of trunks extending from the first office to the second office, a plurality of groups of directors in said first office, the directors of the first group being arranged 100 to extend calls to the second office via the first group of trunks, the directors of the second group being arranged to extend calls to the second office via the second group of trunks, etc., and means effective in case any group of trunks is busy 105 for changing the directors in the corresponding group so that they will trunk calls to said second office via an idle group of trunks.
- 110 86. In a telephone system, a plurality of groups of trunk lines over which calls having a common destination may be trunked, means whereby calls are normally trunked over said groups in substantially equal proportions, and means effective in case one of said groups becomes busy for diverting the calls that would otherwise be 115 directed through this group to a particular one of the remaining groups.
- 120 87. In a telephone system, a plurality of groups of trunk lines for handling calls having a common destination, a like plurality of groups of call 125 directors, each group of directors being arranged to direct the calls handled thereby through a different one of said groups of trunk lines, and means effective in case any group of trunk lines becomes busy for altering the corresponding 130 directors so that they direct their calls through idle ones of said trunk lines.
- 130 88. In a telephone system, a plurality of groups of trunk lines for handling calls having a common destination, a like plurality of groups of call 135 directors, each group of directors being arranged to direct the calls handled thereby through a different one of said groups of trunk lines, and means effective in case a given group of trunk lines becomes busy for altering the corresponding 140 directors so that they direct their calls through a single one of the other groups of trunk lines, said means being effective in case a given other group of trunk lines becomes busy for altering their corresponding directors so that they direct 145 calls through another single one of said groups of trunk lines.
- 150 89. In a telephone system, a plurality of groups of trunk lines for handling calls having a common destination, a like plurality of groups of call

- directors, each group of directors being arranged to direct the calls handled thereby through a different one of said groups of trunk lines, and means effective in case a given group of trunk lines becomes busy for altering the corresponding directors so that they direct their calls through a particular other one of said groups of trunk lines, said means being effective in case said particular group of trunk lines is busy for 5 altering the said corresponding directors so that the calls handled thereby are directed to idle trunk lines in a third group. 90. In a telephone system, a plurality of trunk line groups for handling calls having a common destination, a like plurality of groups of call directors, said call directors being so arranged that each group of directors directs the calls handled thereby to a separate one of said trunk line groups, and means in said directors controlled in 10 accordance with the busy or idle condition of said 20 trunk line groups whereby a group of directors can use another of said trunk groups as a second choice group in case the trunk line group normally used by such directors becomes busy. 91. In a telephone system, a plurality of trunk line groups for handling calls having a common destination, a like plurality of groups of call directors, said call directors being so arranged that each directs the calls handled thereby to a separate one of said trunk line groups, and means in 30 each director controlled in accordance with the busy or idle condition of said trunk line groups whereby another of said groups is used as a second choice group in case the trunk line group normally used by the directors in any given group 35 becomes busy, the last named means being so arranged that in case the second choice trunk line becomes busy or is busy when the first choice trunk line group is busy the calls will be directed through other trunk lines as long as there are 40 other trunk lines idle. 92. In a telephone system, a first office, a second office, three groups of trunk lines extending from said first office to said second office, a director in said first office to translate the office 45 designation of said second office into a code which will trunk a call over a trunk line in the first of said groups, means responsive to a busy condition of said first group for changing the code to cause 50 the call to be trunked over a trunk line in the second group, and means responsive in case both the first and second groups are busy for changing the code a different way so as to trunk the call over a trunk line in the third group. 93. In a telephone system, an automatic switch, a plurality of groups of lines accessible to said switch, sending apparatus for transmitting impulses to bring said switch into operative relation with one of said groups of lines, means responsive to the condition of all lines in said group being busy for altering said sending apparatus so it will send a different series of impulses to bring said switch into operative relation with a second one of said plurality of groups of lines, and means responsive to the condition of all lines in said last group being busy for altering said sending apparatus so that it will send a different series of impulses to bring said switch in operative relation with another one of said plurality of groups of lines. 94. In a telephone system, a first office a second office, three groups of trunk lines extending from said first office to said second office, a director in said first office to translate the office designation of said second office into a code which will trunk a call over a trunk line in the first of said groups, means responsive to the busy condition of said first group for changing the code to cause the call to be trunked over a trunk line in one of the other groups, and means responsive to the busy condition of said latter other group for changing the code to cause the call to be trunked over a trunk line in another one of said groups. 95. In a telephone system, an automatic switch, a plurality of groups of lines accessible to said switch, a sending apparatus for transmitting impulses to bring said switch into operative relation with one of said groups of lines, means controlled in accordance with traffic conditions in said group of lines for altering said sending apparatus so that it will send a different series of impulses to bring said switch into operative relation with another one of said plurality of groups of lines, and means responsive to all of the lines of said latter group being busy for altering said sending apparatus so that it will send a different series of impulses to bring said switch into operative relation with another group of lines.
